MESH MACHINE

Application filed June 27, 1924. Serial No. 722,708.

This invention relates to the manufacture of link mesh fabric, such as commonly used in the manufacture of ladies' hand bags and other similar articles. More specifically, the 5 invention is directed to the provision of a machine for the production of a link mesh fabric of an ornamental character which contains links of different colored metals arranged in the fabric according to predetermined designs or patterns.

Machines of various types are in use at the present time for making link mesh, and on these machines the mesh is produced either in the form of a sleeve or in a flat 10 web or strip. The fabric is composed of links, each of which is intermeshed with a plurality of other links, and in a strip of the fabric there are rows of links arranged both transversely and longitudinally of the 15 piece. These links are usually made of wire of a precious or semi-precious metal, and in some machines the wire is led from a supply to link-forming devices or tools by which lengths of wire are severed and 20 formed into rings or links, intermeshing with those of the piece of mesh. These machines operate with a step by step movement with the link-forming tools operating to insert a link at each period of rest. In 25 some cases, the machine is provided with several sets of tools, thus increasing the rate of production, but at each operation of a set of tools, a single link is formed. In other machines the forming tools are supplied 30 with staples previously made of wire and carried in magazines, of which there is one for each set of tools. A multiplicity of tools is arranged in a bank in the machine, and upon each operation of the tools one complete row of links is added to the 35 mesh at one end. With either type of machine only one kind of wire is used at a time for all the tools, and consequently the fabric produced has a plain, undecorated 40 appearance.

The machine of the present invention is designed to produce ornamental mesh, and is so arranged and constructed that links of different kinds of metal may be incorporated 45 in the fabric during the progress of the

mesh-making operation. These different metals have different colors and the machine is arranged so that various patterns may be formed in the fabric by inserting links of the metals of contrasting colors in a selected 55 order.

The principles of the present invention may be utilized in connection with mesh-making machines of any of the various well-known types, such as those which produce 60 mesh in the form of a sleeve or in the form of a flat strip; those in which the mesh moves either downwardly or upwardly as it is made, and those in which the mesh is produced either a link at a time or a row 65 of links at a time. The type of machine which is considered best for the purpose is that in which the mesh is made in the form of a sleeve which is moved upwardly as the operation of adding links to the piece 70 progresses. This machine is provided, in addition to the ordinary instrumentalities for making the rings and inserting them in the fabric, with a plurality of supplies of 75 different wires, or wires presenting a different surface appearance, and automatic mechanism for controlling the operation of the machine to make links from these different kinds of wire in a predetermined order 80 of succession, to begin making links from any selected wire at a predetermined point in the fabric, and to shift from one wire to another after a predetermined number of links has been made. This automatic mechanism is under the control of a master device 85 which may conveniently include an endless sheet or tape similar to that commonly known as a music roll and which is prepared in advance so that the selected pattern will be made and repeated as often as 90 may be desired throughout the length of the piece of mesh. In mesh-making machines of the sleeve type the wire is fed from a supply to link-forming tools which make 95 and insert links intermeshing with other links at the edge of the cylindrical piece of fabric. These tools operate to cut a piece of wire, bend it to the form of a staple, advance the staple toward the mesh so as to insert its legs through a pair of links at 100

the edge of the piece of mesh, and then close the staple to complete the link. In arranging such a mechanism for use in the manufacture of multi-color mesh, a plurality of supplies of wire is provided, each supply having its own feeding mechanism. These several feeding mechanisms are under the control of the master device, so that wire is fed to the link-forming tools in accordance with the pattern which is to be produced in the mesh. Whenever the pattern calls for the insertion of a link of a certain kind of wire, the feeding mechanism associated with the supply of that wire is brought into action and feeds a length sufficient for a single link. The link-forming devices sever the length fed, form it into a staple and perform the other steps in the insertion and closing of the staple to form a link, whereupon the piece of mesh and the tools are moved relatively to present a new portion of the fabric to the tools. Wire for another link is now fed to the tools and the cycle of operations is again carried on, with each feeding operation controlled by the pattern devices.

The automatic master mechanism which controls the change from one piece of wire to another is driven by the power driven devices of the machine and is actuated in correspondence with the step by step movement of the piece of mesh relative to the tools, and the operation of these tools in the periods of rest of that step by step movement. This master controller at selected intervals functions to discontinue the operation of the feeding mechanism for one supply of wire and to bring into action the mechanism for another supply as may be required by the pattern. Included in the control mechanism is a pattern sheet, preferably endless, and having effective control areas arranged thereon in groups. The mechanism is so constructed that these effective areas are brought successively into operating position group after group and each area governs the formation of a single link, determining the wire which is to be used in making that link. The areas, which may be in the form of projections, or perforations and blank spaces, are so disposed on the sheet that their position and arrangement corresponds in a general way to the position and arrangement of the single links in the fabric, and these areas are of different forms, the number of which corresponds to the number of different kinds of wire which is to be used in making the mesh.

The pattern sheet exercises its control over the wire feeding devices by elements which are moved to varying positions of rest determined by the effective areas and as each link is formed a new area is brought into operating position and the mechanism functions in such a way that the wire feeding

device for the supply of wire of which the next link is to be made is rendered effective in accordance with that kind of area which is brought into action. The mechanism may include a movable finger which cooperates with the pattern sheet moving to a position of rest which is determined by the area which lies in effective position. This movable finger has as many different positions of rest as there are different kinds of wire, and in each position of rest it causes one of the wire feeding devices to operate while the others remain inoperative. In the course of the mesh-making operation, the link-forming tools and the piece of mesh are given a step by step relative movement with the tools operating in each pause of the movement. The pattern sheet and the movable finger have a corresponding step by step movement and at each pause in this movement the finger comes into contact with a sheet, thus assuming a position of rest determined by the effective area of the sheet which is presented to it. With the finger in its position of rest as determined by the pattern sheet, a length of wire from the supply which is selected by the area presented to the finger is fed to the link-forming tools and a link of this wire is inserted in the fabric in the usual way. Thereupon the finger is displaced from the pattern sheet and another step in their intermittent relative movement takes place, whereupon the finger is again brought into contact with the next successive area in the group and another link is formed from the selected kind of wire. When all the areas in a group have been brought successively into position, the pattern sheet and the finger are given a relative movement sufficient to cause a new group of areas to be brought in registry with the finger, whereupon a step by step relative movement similar to the one first described is given the pattern sheet and finger and the areas in the new group are successively brought into action.

In the machine which has been illustrated in the drawings, which will presently be described in detail, two sets of link-forming tools are employed, located at diametrically opposite points on the sleeve of mesh, and these tools add links one by one in successive rows, so that when the sleeve has made a complete rotation past the tools, two rows of links have been added at the end of the piece of mesh. Since the feeding of wire to each of these link-forming tools must be controlled, there is one finger for each set, and the pattern sheet which is used in this type of machine has its effective areas arranged in double groups so that at each step in the relative movement of the fingers and the sheet, two areas in the group are presented to the fingers. The fingers are then moved simultaneously into contact with

these areas and the wire which is fed to each set of tools is controlled in the usual way.

In this machine, three different kinds of wire are used for making links, consequently the effective areas are in three different forms and whichever form of area is presented to the finger will bring about the feeding of the corresponding kind of wire to that set of tools.

The mechanism by which the finger transmits its control action to the wire feeding devices includes appropriate mechanism for producing a relative movement of the finger and sheet so as to move the finger out of contact with the areas on the sheet, then a second relative movement to cause the next successive area to be brought into effective position relative to the finger, thereupon the finger and sheet are moved relatively so that the finger assumes a position of rest as determined by the area. With the finger thus at a controlled position of rest, mechanism is actuated by which each of the feeding devices would be caused to feed a length of wire, but the finger in assuming this position of rest has caused all but one of these devices to become ineffective so that the actuating mechanism for all of the feed devices operates at the appropriate time, but only one of the feeding devices causes wire to be delivered to the tools.

The several groups of mechanism are provided with appropriate driving connections which are necessarily co-ordinated in action to permit the several instrumentalities to perform their functions in the proper time relation. As the link-making operation proceeds, the pattern sheet determines the kind of wire which will be used in each link throughout the fabric. Accordingly, mesh of any desired pattern may be produced, and by a suitable arrangement of the machine, as many different kinds of wire may be used as may be desired. The pattern which is produced will depend on the formation of the pattern sheet and the latter may be prepared in advance so that a mesh having plain portions or stripes or figures of any degree of intricacy will be formed. Also, since the change from one type of mesh to another simply involves the removal of the pattern sheet, as will presently be described, the machine is not put out of action for any considerable length of time by such a change.

In the accompanying drawings, one embodiment of the invention is illustrated, the machine being one which produces three color mesh in the form of a sleeve. In these drawings,

Fig. 1 is a top plan view of the machine,

Fig. 2 is a plan view of the machine with the bed plate removed, and showing certain parts in section,

Fig. 3 is a vertical, longitudinal cross-section of the machine,

Fig. 4 is an end view of the machine looking toward the right in Fig. 1,

Fig. 5 is a transverse sectional view on the line 5—5 of Fig. 1,

Fig. 6 is a plan view of the pattern mechanism shaft,

Fig. 7 is a detail view illustrating the action of the control bars,

Fig. 8 is a vertical sectional view through the pattern sheet support,

Fig. 9 is an end view looking to the right in Fig. 8,

Fig. 10 is a view, partly in section, of a detail of the control mechanism,

Fig. 11 is a sectional view through the pattern sheet support and certain associated parts of the pattern mechanism.

Fig. 12 is a plan view of a portion of the pattern sheet,

Fig. 13 is an end view of a wire-feeding device,

Fig. 14 is a front view of the same,

Fig. 15 is a top plan view of the feeding mechanism with certain parts removed,

Fig. 16 is a face view of a movable wire block,

Fig. 17 is a view showing the delivery end of the same,

Figs. 18, 18^a, and 19 are side, perspective, and front views respectively of a modified form of wire feeding device, Fig. 18^a showing a detail only.

Figs. 20 and 21 are face and front end views, respectively, of a modified type of wire guide block used in connection with the wire-feeding mechanism shown in Figs. 18 and 19.

Fig. 22 is a top plan view of the mechanism by which the pattern sheet is caused to be moved in correspondence with the movement of the mesh,

Fig. 23 is a transverse sectional view on the line 23—23 of Fig. 22,

Figs. 24 and 25 are longitudinal sectional views, taken on the lines 24—24, and 25—25, respectively, of Fig. 22.

Fig. 26 is a view similar to Fig. 22, but showing the parts in different relation,

Fig. 27 is a sectional view on the line 27—27 of Fig. 26,

Figs. 28 and 29 are longitudinal, sectional views of the mechanism taken on the lines 28—28 and 29—29, respectively, of Fig. 26,

Fig. 30 is a plan view of the mechanism illustrated in Figs. 22 and 26, but showing the parts at a later stage in the cycle of movement,

Fig. 31 is a transverse, sectional view on the line 31—31 of Fig. 30,

Figs. 32 and 33 are longitudinal, sectional views on the lines 32—32 and 33—33, respectively, of Fig. 30,

Fig. 34 is a view similar to Fig. 30, but

showing the relative position of the parts at a later stage in the cycle of operation,

Figs. 35 and 36 are longitudinal, sectional views taken on the lines 35—35 and 36—36, respectively, of Fig. 34,

Fig. 37 is a view similar to Fig. 34, but showing the parts at the half-way point in the cycle of operations,

Figs. 38 and 39 are longitudinal, sectional views on the lines 38—38 and 39—39 respectively, of Fig. 37.

Referring to these drawings, the machine is seen to be provided with a table or bed plate 40 which is supported above the floor by legs 41, at any convenient height. Mounted centrally on the table are the instrumentalities for making the mesh, which include a block 42, which is cylindrical in form and is secured in place in an aperture 15 in the table by means of an etension 43, which is threaded at its lower end and held in place by means of a nut 44. A ring 45 is secured in a channel along the upper edge of the block, and the surface of this ring 20 is provided with a spiral groove. Secured in place on the top of the block by means of bolts 46 is a second block 47 and a ring 48 which lies in a channel in the smaller block 47 is supported so as to run freely on ball bearings 49 which rest on the top of the ring 45. The block 48 is provided with alternate 25 vertical ridges and depressions, and encircling the block 47 and the upper end of the block 42 is a sleeve 50, the inner surface of 30 which is provided with alternate ridges and depressions, also vertically arranged. The sleeve 50 has a flange 51 overlying a ring-like support 52 which is suitably mounted 35 on the table in any convenient manner, and ball bearings 53 are interposed between the flange 51 and the support 52 so that the sleeve may move with freedom. The edge 40 of the flange is provided with ratchet teeth 54, by means of which the sleeve may be given a step-wise movement of rotation by 45 devices which will presently be described.

This links in successive rows in a fabric which is made up of links arranged in a plurality of transverse and a plurality of longitudinal rows, tilt in opposite directions, and this condition is taken advantage of in the present machine in order to provide a support for the mesh. As has been described, the sleeve 50 and the ring 48 have vertical ridges and depressions, and the ring-member 45 is provided with a spiral groove. The sleeve is positioned close to the ring members so that the rings in the mesh will 50 engage in the depressions in the sleeve and also in the spiral groove in the ring 45. Consequently, if the sleeve is given a rotational movement, the mesh which is held between the sleeve and the ring 48 will be caused 55 to rotate and since the links of the mesh

engage in the spiral groove in the ring 45, which is held stationary, the result is that in this rotational movement the mesh is caused to move in the direction of its longitudinal axis. The sleeve of mesh, therefore, moves 70 upwardly in a spiral path, step by step, and the rate of movement is such that at each period of rest a portion of the sleeve of mesh is presented to the link-forming tools, so that new links may be added. In the present machine, there are two sets of these tools disposed at diametrically opposite points in 75 relation to the block 42. These link-forming tools operate simultaneously but add links in successive rows about the mesh so that when the sleeve of mesh has made a complete rotation two complete rows of links will have been added, at its lower end. Consequently, the link 45 has a double spiral 80 groove, and as the sleeve of mesh is formed it passes outwardly beyond the end of the sleeve 50 and the exposed portion 55 may be supported in any convenient manner. The link-forming assemblies are of similar 85 construction, and but one of them need be described.

Supported in brackets 56, which depend from the bed plate 40, is a main drive shaft 57 which carries a pulley 58 at one end, and a clutch 59, which is shown somewhat diagrammatically, so that the pulley may be driven continuously and the shaft may be driven or may remain idle, as may be desired. At the other end the shaft carries a hand wheel 60, so that the shaft may be turned by hand in the event that it is necessary to set the parts in any desired relation, as for instance, if it should be necessary to insert one or more links which have 90 been omitted because of a defect in the wire. The shaft carries near one end a bevel gear 61 which meshes with a similar gear 62 on an upright shaft 63 carried in a bearing member 64, supported in the table. The shaft extends beyond the upper end of the bearing. Between the gear and the lower face of the bearing, which is held in place by a nut 65, is a face cam 66 on which rides a roller 67 in the end of a rod 68. At its upper end the shaft carries a disc 69 between which and the upper face of the bearing 64, is interposed a double row of ball bearings 70. The disc carries a pin 71 disposed eccentrically in its upper surface, and surrounding this pin loosely is a block 72. The block enters a recess formed in a block 73, the lateral edges of which enter guideways 74 formed in upright supports 75, secured to the table. The block 73 enters 110 between the arms of a yoke 76 which is formed by spaced flanges mounted on the rear end of the link-forming tool assembly.

The tool assembly is similar to that regularly employed in mesh machines now in 115

common use, and is supported in a slot 77 formed in the top of the block 73 so that as the shaft 63 is driven by the main shaft the eccentricity of the pin 71 causes the block 5 73 carrying the tool assembly to move toward and away from the central block 42 about which the mesh is formed.

The link-forming assembly consists of a cylindrical housing 78, in the forward end 10 of which is mounted a plunger consisting of a sleeve 79 into which is threaded a tubular member 80, the forward end of which carries prongs, one of which is shown at 81. Anchored in the member 77 in any convenient manner, is a die rod, the forward end of which is shown at 82, this rod extending through a channel formed in the member 77 and through the sleeve 79 and the tubular member 80. The forward end of the die rod 20 has a channel, not shown, but formed on the arc of a circle for the purpose of bending the wire. The tubular member 80, is held in adjustable position in the sleeve 79 by means of a lock nut 83. The housing 78, in which 25 the sleeve 79 is mounted, contains a spring encircling the rod 82, this spring tending to force the sleeve out of the housing, and thus retaining the tubular member 80 resiliently in position with reference to the end of the 30 rod 82. Also threaded on the tubular member 80 is a depending lug 84 held in place by a lock nut 85. The forward end of the tubular member extends through a channel formed in the block 86 and a cap 87 bolted 35 to the block 86 serves to hold the tubular member in place in this channel.

Pivottally mounted in a suitable channel in the block 86 is a rocking lever 88, the forward end of which carries a forming mandrel 89. The rear end of the rocking lever rests on the upper end of the rod 68, the lower end of which carries the roller 67, resting on the face of the cam 66 and as the cam rotates, the lever, the mandrel end of 45 which is normally forced upwardly by the spring 90, is rocked so as to raise and lower the mandrel under the control of the cam 66. Pivottally mounted in a channel in which the forming mandrel end of the lever 88 moves, 50 is a pivoted knife 91 which is rocked by a rocking arm 92, pivottally mounted in the block 86. The arm 92 is caused to rock by means of a vertical rod 93, the lower end of which carries a roller 94, bearing against a cam 95 on the main shaft 57 and a spring 55 96 holds the follower against the surface of the cam. The cam is so arranged that at the appropriate time the knife 91 is rocked so as to cut off a piece of wire which is then 60 acted upon by the tools and bent to form a link.

Referring now to Fig. 5, there is shown in cross-sectional view, a portion of the block 65 86 in which the various parts previously mentioned are mounted, and resting in

the channel in the upper end of this block is a movable guide block 97, against the upper surface of which bears one end of a leaf spring 98, the other end of which is secured to the block 86. The 70 guide block has secured to its lower face a rod 99, passing through a bore formed in the block and resting at its lower end against a pin 100, which passes through a bore in the table 40. The lower end of the pin 100 rests 75 on one end of a rocking arm 101 pivotally mounted on the under surface of the table. The other end of the arm 101 carries a roller 102 which bears against a group of cam surfaces formed on a control bar which will 80 presently be described. The wire block which is shown more clearly in Figs. 16 and 17, is provided with spaced channels 103, formed in one face, the rear end of these channels being covered by a plate 104 and 85 secured to the block in registry with the channels so as to form continuous passages therewith, are tubes 105. Through these tubes are fed the wires which are to be delivered to the link-forming devices and as 90 the present machine is designed to make use of three kinds of wire, there are three channels and three tubes 105, each of which communicates with one of the wire-feeding devices. These tubes are provided so that the 95 wire may be led from the feeding devices to the block without kinks or sharp bends being formed in it. The front end of that face of the block in which the channels are exposed, lies against a plate 106 secured in the 100 block 86, and the knife member 91 is so disposed that as the wire is fed beyond the end of the block 97 at the appropriate time the knife member rocks and severs a length of 105 wire close to the face of the guide block. As 110 is shown in Figs. 1 and 5, a wire stop 107 is mounted in a bore in the block 86, in opposed relation to the wire guide block 97, this stop being held in position by means of a leaf spring 108, secured to the face of the block 86. As the wire is fed through the 115 guide block its end abuts the end of the stop member 107 and when the exposed length of wire is severed the spring pressure of the stop 107 holds the severed length of wire in place until it can be taken up by the tools.

Mounted in a horizontal bore in the block 42 in registry with the outer die member, is an inner die rod 109, the end of which has a semi-circular channel adapted to receive the ends of a staple of the wire, and, in cooperation with the outer die member, to bend these ends together to close the staple to form a link. This inner die member extends into a central vertical passage 110 in the block 42 in which moves a rod 111, the lower end of which has a roller 112 bearing on a cam 113 on the shaft 57. The upper end of the rod 111 has a cam surface 114 which bears 120 against the rear end of the die member 109. 125

A leaf spring 115 secured on the block 42 bears against a shoulder formed on the inner die member, and maintains the latter against the cam surface 114. The roller on the end 5 of the rod 111 is held against the surface of its cam by means of a spring 116, which lies in a recess in the upper block 47.

The link-forming devices which have now been described, operate as follows. When 10 the sleeve of mesh which is moved with a step-wise rotation, comes to rest, a length of wire is fed from the selected supply, and passes beyond the outer face of the wire guide block into the channel in front of the die members. The end of this exposed 15 length of wire bears against the spring-held wire stop 107. The knife member then swings about its pivot, severs the exposed length of wire, and shortly thereafter the outer die member moves forwardly so that 20 the prongs 81 bear against the severed length of wire. In the meantime the forming mandrel 89 has moved up into position and the prongs of the outer die member bearing 25 against the wire, bend the latter around the forming mandrel, the wire, which then takes the form of the staple, being forced into the channel in the end of the die rod between the prongs 81. The forming mandrel 30 is then lowered by the rocking of the arm 88 and the outer die member moves forwardly. The ends of the staple are now 35 in the proper position so that they may be inserted through a pair of links at the edge of the mesh, and at the proper time the inner die member 109 is moved outwardly by the raising of the cam rod 111 so as to provide 40 an abutment against which the ends of the staple, which have been passed through a pair of links, come in contact, so as to cause 45 these legs to be bent toward each other to complete the ring. At the proper instant, however, the lug 84 has engaged a stop lug 117, formed on the end of the block 86, which causes the outer tubular member 50 to be held stationary, thus permitting the inner member 82 to force the staple out beyond the ends of the prongs 81. The legs of the staple, having been inserted through a 55 pair of links at the edge of the fabric, and these legs bent toward each other so as to complete the ring or link by the cooperation of the inner and outer die rods, the two die rods move apart, thus releasing the link. The mesh support now advances another 60 step so as to present a new pair of links to the die rods, whereupon the various parts repeat their functions and the next link is added. These parts are all operated by cam devices which are appropriately timed so 65 that the mesh-making operation may progress without interruption.

The mesh is moved past the tools with a step-wise rotation by the movement of the outer sleeve 50, which has, at its upper end,

a flange with ratchet teeth 54 formed on its rim. This is shown more clearly in Fig. 1. The supporting ring 52 on which this sleeve 50 runs is provided at opposite points with bearing lugs 119 and 120. The bearing lug 70 120 supports the upper end of a rock shaft 121 (see Fig. 2) the lower end of which is appropriately journaled in the table. This rock shaft carries a lug 122 at its lower end in which is carried a roller 123 which bears 75 against the surface of the cam 124 on the main drive shaft. Another lug 125 provides a nut for one end of a spring 126, the other end of which is secured to the table, this spring tending to hold the shaft in such position as to force the roller against the face 80 of the cam. At the upper end the shaft 121 carries a block 127 with a longitudinal channel formed in it. In the front end of the channel is secured a pawl 128 which is 85 placed so as to engage in the ratchet teeth 118. This pawl has a rearward extension lying in the channel in the block 127, and also has a pin 129 which extends upwardly through a slot formed in the upper face of 90 the block. Disposed in a recess in the block 127, behind the extension of the pawl, is a spring which holds the pawl in operative position. As the shaft 121 is rocked by the cam 124, in one movement the pawl engages 95 one of the ratchet teeth and advances the sleeve 50 by one tooth. In the rearward movement the pawl rides over the teeth. Each ratchet tooth corresponds to a link in 100 a row around the sleeve of mesh so that upon the sleeve being advanced by one tooth, a portion of the mesh is presented to the link-forming tools in appropriate position to have a new link added to it. Mounted in the bearing lug 119 is a block 130 which carries 105 at its outer end a leaf spring 131 which engages in the teeth of the ratchet and prevents any retrograde movement of the sleeve of mesh as the pawl rides over these teeth.

The devices by which wire is fed from 110 a selected supply to the link-forming tools will now be described. The supply of wire is carried on the machine at any convenient location in the form of reels, which are not shown in the drawings. The wire is drawn from each of these reels and fed to the link-forming tools by means of a pair of rolls. The construction is illustrated more clearly 115 in Figs. 13 and 14. The rolls 132 and 133 are mounted in pairs in a channel formed 120 in the block 134 mounted on the table 40. The shaft of the lower roll is mounted in suitable bearings formed in the block 134, while the upper roll is carried in a movable bearing in a slot 135 formed in the block 134. A pair of coil springs 136 bear against 125 the movable bearing so as to hold the upper roll 132 against the lower roll 133. The circumferential channels 137 formed in the two rolls are of such size that the rolls 130

which are forced together by the pressure of the springs 136, will grip the wire with a slight pressure. On one end of the shaft of the lower roll is a gear 138, while the shaft 5 of the upper roll carries a similar gear 139, meshing therewith. On the other end of the shaft of the lower roll is a ratchet wheel 140 and a rocking arm 141 is loosely mounted on the end of this shaft. This 10 arm carries a pawl 142 pivotally mounted on the arm and held against the teeth of the ratchet 140 by means of a leaf spring 143. The arm 141 is connected by a link 144 to the upper end of a rocking 15 arm 145, the lower end of which, as shown more clearly in Fig. 5, is fast on a rock shaft 146 appropriately supported from the bed of the machine. This rock shaft also carries an arm 147 having a roller 20 148 at its outer end, which bears against a cam 149 on the main drive shaft. As the cam 149 revolves, the rock shaft 146 is caused to rock and the arm 145 swings the smaller arm 141, thus causing the pawl 25 142 to move back, engage a new tooth of the ratchet and then, in its forward movement, rotate the ratchet to the extent of one tooth. By the movement of the ratchet the lower roll is caused to revolve and the upper roll 30 is also revolved with it by reason of the meshing of the gears 138 and 139. The ratchet wheel 140 is so formed that whenever it is advanced by one tooth a sufficient amount of wire is drawn from the supply 35 by the feed rolls 132 and 133 for the formation of a single link. In the present machine there are two sets of link-forming devices and there are three supplies of wire which are to be fed selectively to each of these 40 devices. There is one rock shaft for all of the supplies of wire which is to be fed to one set of tools, and in the present instance there are two rock shafts placed end to end beneath the table of the machine, each rock 45 shaft being driven by an arm 147 on a cam 149. Each rock shaft carries three arms 145 to actuate a pawl associated with each of the three pairs of wire feeding rolls, but since wire is fed only from one supply at a 50 time and since all of the pawls 142 are moved in unison, means must be provided to render two of these pawls ineffective at each feeding operation. Accordingly, each of the wire feeding devices is provided with 55 a rod 150, disposed in a suitable channel in the face of the block 134. This rod has a pin 151, which is located just beneath the pawl 142, so that when the rod is raised the pin will strike the pawl and lift it clear 60 of the teeth of the ratchet wheel. Consequently, when the rod is in the upper position the pawl with which it is associated becomes ineffective and though the pawl 65 may be rocked by the arm 145 the feed rolls are not caused to rotate. At its lower end the rod 150 bears against a pin 152, which enters a bore formed in the table. The lower end of the rod 152 is pointed, as indicated at 153, and bears against the upper surface of a control bar 154. This control 70 bar is provided with recesses in its upper surface and is so arranged that it may be reciprocated to different longitudinal positions of adjustment and in any given position one of the three rods 152 will enter 75 a recess, thus causing the pawl corresponding thereto to drop into engagement with the teeth of the ratchet 140. The longitudinal positions of adjustment of the control bar 154, therefore, determine which of 80 the wire-feeding devices will be effective and thus determine the kind of wire of which a link will be made at any instant in the progress of the mesh-making operation. 85 Since control is to be provided for the kind of wire which is to be fed to each of the sets of link-forming tools, two control bars are made use of, as shown in Fig. 7. Each of these control bars is disposed in a channel 155, formed in the lower surface of the 90 table 40, and the control bars are forced toward each other by springs 156, one end of which is secured to a pin 157 attached to the bar and the other to a pin 158 attached to a stationary part of the bed plate. As the 95 two control bars are actuated by similar devices only one set of these devices will be described. A cam plate 159 is mounted in a suitable channel in the bed plate of the machine and is movable transversely of the 100 control bar. The inner end of the control bar is beveled as indicated at 160, and this end bears against one face of the cam plate. The cam plate has cam surfaces 161 formed 105 in steps of four different heights and as the cam plate is moved to different positions transversely with relation to the control bar the inclined surface of the control bar rides over these steps which are inclined, as indicated. The position of adjustment of the 110 control bar is consequently determined by the position of the cam plate since the end of the bar rests on these surfaces which are of varying heights. In Fig. 2 the cam plate at the left is in such a position of adjustment 115 that the control bar rests against the lowest cam surface, and, as shown in Fig. 7, in this position the first notch 162 in the control bar is in a position to receive a pin 152 so that this pin drops down, thus lowering the rod 150 and permitting the pawl 142 associated 120 with that rod to be effective. Consequently, with the control bar 154 in the position illustrated at the left in Fig. 2, wire will be fed from the first of the three supplies. The cam plate at the right in Fig. 2, however, is in a different position of adjustment so that the control bar rests against the second cam surface, and, as shown in Fig. 7, in this position 125 it is the second of the three pins 152 130

which is received in the notch 162 in that bar. Consequently, the second supply of wire will be fed to the right-hand set of tools. The third cam surface on each of the 5 cam plates would permit the third supply of wire to be fed, while the fourth, indicated at 163, is so arranged as to throw all of the wire-feeding devices out of action.

On the lower surface of each of the cam 10 bars is a plate 164, provided with areas of different heights, also serving as a cam. This plate provides cam surfaces against which bear the roller 102 on the end of the arm 101. This arm bears against the pin 15 100, which, in turn, bears against the lower end of the arm 99 secured to the movable arm block as shown in Fig. 5, and, therefore, as the roller 102 rides over these cam surfaces the arm 101 will be rocked to different 20 positions of adjustment, thus bringing one or the other of the passages in the wire block into registry with the stop 107 and also into proper position to deliver wire to the link-forming devices. The control 25 bar, accordingly, exercises control over both the wire-feeding devices and the movable wire block, since in the first instance the position of the control bar determines which of the wire feeding-roll ratchet pawls will 30 be effective, and in the second instance it determines which of the channels in the wire block will be in registry with the link-forming devices. The series of recesses 162 in the upper surface of the control bar, forms 35 one group of cams, while the plate 164 provides a second group and these groups of cams are arranged in proper position so that whenever wire is being fed from one of the supplies of wire the passage in the movable 40 wire block through which that wire passes will be in registry with the link-forming tools.

The position of the control bars 154 has 45 been explained to be determined by the position of the cam plates 159, and the position of the latter is determined by the pattern mechanism now to be described.

As shown in Figs. 1 and 4, the shaft 165 is mounted at one end in the bracket 166 50 to the rear of the machine, the other end of the shaft being also supported in a similar bracket which carries the devices by which the shaft is moved longitudinally with a step by step movement. This shaft is shown 55 in Fig. 8 as made in two parts and one end of the shaft carries a sleeve 167 while the other end of the other part of the shaft carries a similar sleeve 168. Mounted to revolve on each sleeve is a sprocket wheel 169 having a row of teeth 170 and a circumferential flange 171 disposed at one side of the teeth. Secured to each of the sprocket 60 wheels 169 on the outer face thereof, is a ratchet wheel 172 which is free to rotate 65 about the sleeve 167. Between the sprocket

wheels and encircling the inner ends of the sleeve 167, is a hollow cylindrical member 173, secured to the sprocket wheels by screws 174. The cylindrical member 173 has an intermediate portion 175 of reduced diameter. Enclosing the cylindrical member 173 and contacting with the portions of larger diameter thereof, which may be considered to constitute hubs, is a hollow cylindrical member 176, which in part serves to support the pattern sheet. This member is held against rotation by means of an angularly bent plate 177, one end of which is secured to the support 176 and the other to one portion of the shaft 165. The plate 177 also carries a plate 178 between the ends of which is carried an arcuate plate 179, bearing against the face of the sprocket wheel 180 and serving as a friction brake. The pattern sheet 181 shown in Fig. 12, has perforations 182 by means of which the formation of the links is controlled, and also has a row 183 of perforations, along either edge which receive the sprocket teeth 170. The pattern sheet is in the form of a continuous belt, and is placed in position so that the sprocket teeth enter the perforations 183. The sprocket wheels provide a rotary support for the pattern sheet such that the sheet may be advanced in the direction of its 90 length by devices which will presently be described. Centrally the pattern sheet is supported by the cylindrical member 176, held against rotation and this member 176 has channels 184 and 185 which extend entirely across the cylindrical support and are so arranged that at any position of rest of the pattern sheet two rows of perforations will be disposed above these channels. Instead of using the stationary central support 95 having a single pair of channels above which the rows of perforations are successively brought to rest, it would be possible to make use of a support having a plurality of rows of channels spaced about its surface in correspondence with the position of the teeth on the ratchet wheels with which the sprocket wheels are provided. The desired object is to form the support so that a channel lies beneath each row of the pattern sheet when the latter is in effective position 100 so that the fingers entering the perforations will not come in contact with the support 105 for the sheet.

The pattern sheet provides a means by which a selected wire may be fed to the link-forming tools for the production of any single link in the fabric, the devices by which this result is obtained also providing for a movement of the movable wire guide block so that the wire being fed will be properly delivered to the link-forming tools. Since three different kinds of wire are to be used for the links, the pattern sheet must be 115 formed with effective areas of three dis- 120

tinct kinds, so that as these areas are brought successively into position to be rendered effective any one of the three different kinds of wire may be caused to be fed. As the 5 pattern sheet is to control the formation of each link in a row around the sleeve of mesh, there must be as many of these effective areas in a row as there are links in a row around the sleeve. To attain the desired 10 result, the pattern sheet support is moved with a step by step movement in the direction transversely of the length of the sheet, and at each period of rest in the movement an effective area on the pattern sheet is brought 15 into position to exercise its control. These effective areas are of three kinds, small perforations such as 186, large perforations, 187, and unperforated portions of the pattern sheet, not designated. A blank space 20 on the pattern sheet brought into position causes one kind of wire to be fed, a small perforation a second kind, and a large perforation a third kind, and at each period of rest in the movement of the pattern sheet, 25 which, in turn, corresponds to each operation of the link-forming tools, one of these areas is in position to control the feed of wire. Since the operation of each of the 30 sets of tools is to be controlled the effective areas are disposed in double rows. The means by which the control provided by the pattern sheet is transmitted to the wire-feeding devices and the moving wire block, will now be described.

35 Secured to the rear edge of the bed plate of the machine is a bracket 188 which carries a rearward extension 189. In the outer end of the extension is a pin 190 which serves as the pivot of a pair of bell crank 40 levers the inner end 191 of each of which is connected by a link 192 to the end of one of the cam plates 159. Springs 193 secured to these cam plates tend to draw the cam plates inwardly so as to raise the lower 45 arms 191 of the bell cranks. The outer arm 194 of each bell crank is forked, as shown in Fig. 1, and in this forked arm is received a vertically moving pin 195 provided with recesses 196 on its opposite faces, into which 50 the forked end of the arm 194 enters. The walls of the recesses are arcuate so as to permit the arm 194 to move freely about its pivot 190. The pins 195 are mounted in bores in a block 197 which is secured to 55 the rear end of the extension 189 of the bracket 188. These pins are drawn downwardly by means of springs 198, one end of which is secured to a smaller pin 199, extending from the surface of the main pin, 60 the other end to a pin 200 which is mounted in the hub 201 of a rocking arm 202 mounted on a pivot pin 203, secured in the walls of a channel 204, formed in the lower surface of the block 197. The arm 202 has a cam 65 surface 205 having areas of three different heights, and a smaller pin 206 secured in the lower end of the main pin 195, bears against these cam surfaces. At its outer end, the arm 202 carries a finger 207 which has a shoulder 208 near its lower end. This finger 70 is formed on an arc and is so disposed in relation to one of the slots 184, 185, that the arm may be rocked and the finger will enter one of the perforations 186, 187 in the pattern sheet, which is disposed above these 75 slots. There are two such fingers which are placed as shown in Fig. 5, in off-set relation, one being placed so as to enter the channel 184, the other the channel 185, and as different portions of the pattern sheet 80 are brought to rest beneath these fingers the fingers are lowered into contact with the pattern sheet. If a blank portion of the pattern sheet is presented to the finger it will come to rest in the position illustrated 85 in Fig. 11. If a small perforation is presented the extreme end of the finger will enter the perforation until the shoulder 208 bears against the surface of the sheet, whereas if a large perforation is presented the finger will drop downwardly to the bottom of the slot 185. Each finger accordingly has three positions of rest, as determined by the pattern sheet, and these positions of rest of the fingers in turn determine the 90 position of rest of the cam plate and the control bar, and thus determine which wire-feeding device will be rendered effective.

95 Upon the completion of a link by the tools the pattern sheet is to be shifted so as to present a new portion to the fingers. The fingers consequently must be raised out of contact with the sheet and this result is obtained by means of a bell crank 209 pivoted on the shaft 146 and carrying at its outer 100 end a roller 210 which bears against a cam 211 on the main shaft of the machine. The outer end of the bell crank 209 carries a cross bar 212 which is disposed beneath an extending rod 213 mounted on the end 105 of the arms 202. As the bell crank 209 is rocked the cross bar 212 is raised, engages the rods 213, and thus rocks the arms 202 on their pivots 203, raising the fingers 207 out of contact with the pattern sheet. 110 Since the small pin 206 bears against the cam surface 205 on the arm 202 the main pin 195 must be raised so that the small pin will clear the cam surface prior to the raising of the finger, and this result is 115 brought about by means of a second bell crank 214, also pivoted on the shaft 146. At its rear end this bell crank has a cross bar 215, near each end of which is an adjustment screw 216 and at its rear end the 120 arm 217 of the bell crank bears against a cam 218, also carried on the main shaft of the machine. As this bell crank 214 is rocked, its rear end moves downwardly and the adjustment screws bear against flat sur- 125 130

faces 219 on the bell crank arms 191. These arms, being rocked downwardly, cause the rear arms 194 to be raised and since these rearward arms enter the recesses 196 in the pins 195, these pins are lifted so that the small pins 206 at their lower ends are raised clear of the cam surfaces 205. By properly designing the cams 211 and 218 the parts are caused to work in timed relation so that whenever the pattern sheet is to be shifted the bell crank arms 194 are first raised so as to cause the pins 195 to be lifted clear of the cam surfaces on the arms 202 and thereafter the fingers 207 are raised by the arms 209, thus clearing the pattern sheet altogether. The pattern sheet support may then be shifted so as to bring the next effective area into position, and the fingers are now brought to rest against the pattern sheet, either bearing on a blank space or entering a small or a large perforation, as the case may be. The bell cranks 191 are now rocked so as to lower the pins 195 against whichever of the cam surfaces on the cam member 205 is in effective position, this position being determined by the position of rest which is assumed by the finger 207. The position of rest which is assumed by the pins 195 determines the position of rest of the bell crank arm 191 and this position of rest, in turn, is transmitted to the cam plates 159, by means of the links 192. The cam plates determine the positions of rest of the control bars 154, and thus the effective areas of the pattern sheet which are successively brought beneath the fingers 207, determine which of the wire-feeding devices will be effective and place the wire guide blocks into positions so that wire fed from this source of supply will be properly delivered to the tools.

The purpose of having the effective areas, either perforations or blank spaces on the pattern sheet, arranged in two rows is to permit the wire to be fed to each set of tools to be individually controlled and since each link is formed under the control of the pattern sheet it follows that mesh of any desired pattern may be produced, since the material which is to be employed in each individual link may be determined in advance. It will be understood that the utility of the invention is not limited to any specific number of different kinds of wire, nor to any definite number of sets of forming tools. If four sets of forming tools were employed, the feeding of wire to each of which was to be individually controlled, then there would be employed four control bars, and the position of rest of each control bar, which, in turn determines the kind of wire to be fed, would be determined by an individual portion of the pattern sheet. Also, if more than three kinds of wire were to be employed, then additional wire-feed-

ing devices would be necessary and the control bar would be formed so as to feed from any selected one of these supplies of wire, as determined by the pattern sheet. The latter, however, would have to have effective areas of as many different kinds as there were kinds of wire, and this could be provided for by the use of perforations of different sizes with additional shoulders formed on the fingers which cooperate with the pattern sheet. The necessary changes to adapt the invention for use with additional supplies of wire or additional sets of forming tools involve, to a large extent, duplication of parts, and could be made without substantial modification of the machine.

The pattern sheet, a portion of which is illustrated in Fig. 12, is seen to have transverse double rows of perforations and blank spaces, and this pattern sheet is moved past the fingers with a step by step movement in a direction transversely of the length of the pattern sheet, in correspondence with the operation of the link-forming tools. There are as many effective areas or perforations in a row across the pattern sheet as there are links in a row around the sleeve of mesh and whenever a row of links has been added to the mesh a traverse of the pattern sheet past the fingers is completed. The next movement of the pattern sheet is one in the direction of its length so as to present effective areas in the next double row to the fingers. When this double row of areas has been brought into position a return transverse movement of the pattern sheet begins, and continues until another double row of links has been added to the sleeve of mesh. At the end of this traverse the pattern is again moved one step in the direction of its length, each of these lengthwise steps corresponding to a double row of perforations, and then the pattern sheet is caused to move with another transverse movement. Consequently by the action of a device which will presently be described, the pattern sheet passes through the machine with a zig-zag motion. It moves transversely of the machine with a step by step motion, each step of which corresponds to one operation of the link-forming tools until a double row of links around the sleeve of mesh has been completed, and the next operation of the link-forming tools at the end of this traverse is accompanied by a longitudinal advance of the pattern sheet by one step. The cycle of operations of these devices which produce this zig-zag movement of the pattern sheet is continuously repeated so that the pattern sheet eventually makes a complete movement past the fingers, whereupon a piece of mesh having a complete pattern formed in it is produced. As the pattern sheet is endless, similar pieces of mesh will be produced by the further operation of the

machine, and each of these pieces will have a pattern formed in it which is an exact duplicate of that formed in all of the others because of the manner in which the mesh is formed.

The mechanism by which the travel of the pattern sheet is produced is carried on a bracket 220 mounted at any convenient point on the machine, preferably on one of the legs 41, somewhat below the level of the bed plate 40. This bracket is provided with an off-set portion or plate 221 centrally from the rear edge of which extends a plate 222. This plate 222 has a transverse channel 223 in which lies the shaft 165, on one end of which is mounted the pattern sheet support. This shaft has an upper flat surface and teeth 225 are formed in its front edge. Mounted on the top face of the bracket, and held in place by guides 226, is a reciprocating lever 227, one end of which carries a roller 228 which bears against a cam 229 on the main shaft of the machine.

Referring now to Figs. 22 and 25, inclusive, it will be seen that there is pivoted near one edge of the plate 221, at one end thereof, a crank 230 having an arm 231 which carries a knob bearing against the end of the lever 227. The hub of the crank 230 through which extends the pivoting pin, which may conveniently take the form of a bolt, lies in a circular recess 232 in the plate 221, and oppositely disposed on this hub are lugs 233. As the arm 227 reciprocates, the crank 230 is rocked on its pivot and the oppositely disposed lugs also reciprocate in opposite directions. The plate 221 is provided with transverse dove-tailed channels, in each of which moves a slide 234 and 235. These slides are recessed, as at 236 and 237. The crank 230 is pivotally mounted in its recess 232 between the slides and the lugs 233 enter suitable portions of the recesses 236 and 237, so that as the crank is rocked the slides 234 and 235 are moved in opposite directions by the lugs 233. As shown in Figs. 24 and 25, each of the slides has a depending flange 238 formed at one end and between this flange and the plate 221 is a spring 239. These springs tend to oppose the movements of the slides and consequently tend to rock the crank 230 on its pivots, thus holding the lever 227 against the face of the cam 229.

Pivotedly mounted on the slide 234 is a pawl 240, the end of which, under the proper conditions, may engage the teeth 225 in the shaft 165 so that when this pawl is in operative position the movement of the slide 234 will cause the pawl to advance the shaft as the slide moves. The pawl 240 is held in place by a pivot pin in the form of a bolt and extending through this pivot pin is a spring wire 241. Mounted on the slide 234 between spaced pins 242 is an arcuate plate 243. The ends of the plate are slotted, as

at 244 and in these slots are received the pins 242. The arrangement is such that the plate may be moved relative to the slide by appropriate mechanism. The plate 243 has its center portion bowed so that in this movement it will not interfere with the pivot pin of the pawl 240, and along the edge of the plate next to the pawl at either end of the plate are cam surfaces 245 which are arranged to receive the ends of the wire spring 241. When the plate is in that position on the slide shown in Fig. 22, the left-hand end of the spring 241 bears against the upper cam surface 245, the right-hand end of the spring bearing against the lower cam surface. The pawl is now in position so that its end does not engage the teeth 225. When, as will presently be described, the pawl is to become effective, the plate 243 is moved along the slide so that the right-hand end of the spring will ride into the upper cam notch and the left-hand end into the lower. In this position the pawl is swung on its pivot to such an extent that its end may engage with the teeth 225, and when the slide is moved to the right the pawl will carry the shaft with the slide, but on the return movement of the slide the spring permits the pawl to rock on the pivot slightly so as to ride over the teeth. The slide 235 has a similar plate 246 also mounted between spaced pins and capable of movement relative to the slide 235. The pawl 247, formed of two members which are relatively adjustable by means of a screw 248, is carried on a pivot pin 249 on the slide 235, and this pawl also has a spring wire 250 which may engage in suitable cam surfaces in the plate 246. As shown in Fig. 22, the plate 246 is in its right-hand position relative to the slide 235 and the end of the pawl 247 is accordingly in engagement with the teeth 225. Consequently, as the slide 235 moves to the left the shaft 165 will be carried along by the pawl and when the slide returns the end of the pawl will ride over the teeth on the shaft.

The devices by which one or the other of the pawls is rendered effective, will now be described. Mounted in spaced relation on a rod 251 which is carried in the rear end of an extension 252 from the plate 222, are rocking arms 253, 254, 255, and 256. The plate 251 overlies the shaft 165 and carries at its forward end a plate 257 which extends across all of the rocking arms. The plate is provided with recessed projections 258, one for each of these arms, and within each projection is a spring 259 bearing down against the top of the arm so as to force it downwardly on the pivot rod. The arms 254 and 255 carry lugs 260 extending from their lower surfaces, these lugs bearing against the flat upper surface of the shaft 165. Near each end of the latter, as shown in Fig. 6, is a channel 261, in which is adjustably

mounted a plate 262, the rear end of which has a sloping surface 262'. This plate is in position so that as the shaft moves to the left or right, eventually one of the plates 262
 5 will pass beneath the lug 260, whereupon this lug will drop down into the depression 262'. As shown in Figs. 24 and 25, the arm 254 carries a pin 263, which extends beneath the arm 253 so that the latter is held in its upper position until the arm 254 has dropped.
 10 The arm 255 carries a similar pin 264 by which the arm 256 is prevented from dropping until the arm 255 has been lowered.

In Fig. 22 the lever 227 is in its rearmost position and when it is moved forward, as shown in Fig. 26, the slide 234 is moved to the right, and the slide 235 to the left against their springs. When the arm 227 moves forward the springs restore the slides to their original positions, thus moving the crank 231 to its original position, as shown in Fig. 22. When the slide 235 is in the position shown in Fig. 26, the pawl 247 has moved over a tooth on the shaft 165 and when the slide is moved to the left by lever 227 the pawl, engaging a tooth, causes the shaft 165 to advance one step. During this movement of the shaft the lugs 260 on the arms 254 and 255 resting on the flat upper surface of the shaft, keep the arms raised, and these arms, through their pins 263 and 264, in turn keep arms 253 and 256 raised. As the movement of the shaft progresses, as for instance, to the left in Fig. 26, the surface 262' at the end of the plate 262 passes beneath the lug 260, whereupon the arm 254, pressed down by its spring 259, causes the lug 260 to move down the surface 262'. At this time the right-hand end of the plate 246 on the slide 235 has passed beneath the end of the arm 254 so that the latter moves downwardly in front of the end of this plate, as shown in Fig. 28. The arm 253, normally supported by the pin 263 mounted on the arm 254, would now be free to drop but for the fact that the right-hand end of the plate 243 lies beneath it, as shown in Fig. 29. At this time the fingers which control the wire feed, and are in turn controlled by the pattern sheet, are in contact with the effective areas on the pattern sheet at the extreme edge of the latter, and a link is made in the usual manner. The cam 229 now permits the springs on the slides to return the slides to their original positions. As the slide 235 moves to the right it will be seen that the arm 254 lies in the path of movement of the plate 246 so that the latter is held against movement with the slides. The consequence is that the plate 246 is moved on its pins to the position illustrated in Fig. 30, where it will be seen that the right-hand end of the spring wire 250 associated with the pawl 247 has ridden up the cam surface of the arcuate face of the plate.

246 so that the pawl 247 is turned sufficiently to place it in inoperative position with regard to the teeth 225. The pawl 247 is, therefore, out of action. The slide 234 which carries the pawl 240 moves to the left with a movement simultaneous with that of the slide 235, but since the arm 253 bears against the top of the right-hand forked end of the plate 243, this plate moves with the slide 234 without change in its relative position thereon. At this time, therefore, both pawls are out of action, but as the slide 234 continues to the left, carrying with it the plate 243, near the end of its movement to the left the right-hand end of the plate 243 will ride out from beneath the lower face of the arm 253 so that the latter may then be pressed down by its spring and bear against the face of the slide in front of the end of the plate.

Upon the next reciprocation of the lever 227, the slide 235 moves to the left with its pawl still out of action and as the slide 234 moves to the right the plate 243 is held against movement because the end of the arm 253 has moved downwardly in front of the end of the plate. Consequently in this movement of the slide the plate 243 changes position relative to the slide, and in this change of position the wire spring 241 is changed from one pair of cam notches to another so as to cause the pawl 240 to be rocked into active position. The parts are now in the relative positions illustrated in Fig. 34, wherein it will be seen that the arms 253 and 254 are both depressed, the plate 243 is moved to the left-hand position relative to the slide 234, so that its pawl is effective, and the plate 246 is also in the left-hand position on the slide 235 so that the pawl 247 is ineffective. The cam 229 now permits the crank 230 to rock again, and the slide 234 moves to the left, carrying its pawl 240 over one tooth of the series 225. The slide 235 moves to the right without effect. Upon the next reciprocation of the lever 227 the slide 234 is carried to the right and its pawl 240, being in engagement with one of the teeth 225, advances the shaft 224 to the right by one step. Upon the forward movement of the lever 227, the crank 230 is rocked by the slide springs, the pawl 240 slips over a tooth 225, and upon the next rearward movement of the arm lever 227 the shaft 165 is advanced one more step. The movement of the shaft 165 has brought the plate 262 under the lug 260 at the appropriate time so that the levers 253 and 254 are raised out of the way of the slides 243 and 246. Consequently the movement of the shaft to the right is continued without interruption until the second plate 262 at the left-hand end of the shaft comes into action in the manner described.

It will thus be seen that the cam 229 130

actuates a device which advances the pattern sheet past the fingers with a step by step movement which corresponds to the operation of the link-forming tools. Each time the cam 229 makes a complete revolution the slides 234 and 235 also make a complete to-and-fro reciprocation, and the shaft 165 is advanced in one direction or the other, depending on which of the pawls 240 and 247 is operative. When the shaft 165 has reached its limit of longitudinal movement the last step in that movement permits either the arm 254 or 255, as the case may be, to drop, assuming, for purposes of clearness, that the shaft 165 is moving toward the left, as illustrated in Fig. 22. When the last effective area on the pattern sheet is to be moved beneath the fingers, the rotation of the cam 229 carries the slide 235 to the left, as shown in Fig. 26, so that the right-hand end of the plate 246 passes out from beneath the end of the arm 254. The pawl 247 is engaged with a tooth of the shaft 165 during the movement of the slide and as the shaft is moved it brings the surface 262' on the plate 262 beneath the lug 260 on the arm 253. The arm 253 is now free to be forced down by its spring, since its outer end is clear of the end of the plate 246, and its lug 260 is no longer in contact with the upper face of the plate 262. As the cam 229 completes the revolution the slides are restored to their normal positions, as illustrated in Fig. 30, but in this movement of restoration the pawl 247 is taken out of action and the pawl 240 has not yet been brought into action. Upon the next rearward reciprocation of the lever 227, the slides are again moved and the pawl 240 is made effective because the lever 253 has rocked the movement of the plate 243 so as to shift the pawl wire spring 241 from one pair of cam notches to the other, but this result is only brought about at the end of the movement of the slide so that although the pawl 240 is effective at this instant, as shown in Fig. 34, it has produced no movement of the shaft 165 to the right. When the cam makes another half revolution to its forward position, as shown in Fig. 37, the slides are restored to their original positions and the pawl 240 slips back over a tooth. In the next half revolution of the cam the pawl 240 moving with the slide 234, advances the shaft by the amount of one tooth toward the right. It will thus be seen that at the end of the travel of the shaft 165, there is one revolution of the cam 229 corresponding to the formation of a link during which the pattern sheet support has not been moved transversely relative to the fingers, and without any further movement of the pattern sheet the result would be that two links would be formed under the control of the same effective areas of the pattern sheet and then, when the return movement of the shaft 165 commenced, the same effective areas of the pattern sheet would be passed successively beneath the fingers, but in the reverse order. Accordingly, during the time when the rotation of the cam 229 is producing the change in the relative positions of the different parts, such that one pawl is made effective and the other put out of action, some provision must be made for shifting the pattern sheet relative to the fingers, and this period of rest in the movement of the pattern sheet in a direction transversely of its length, is taken advantage of in order to produce a movement by one step of the pattern sheet in the direction of its length, thus bringing another double row of effective areas on the pattern sheet into position to be presented to the fingers. This advance of the pattern sheet by one step in the direction of its length presents to the fingers the first pair of effective areas in the next double row, and thereafter when the pattern sheet is next caused to move transversely with a return movement, successive pairs of effective areas of this succeeding double row are presented to the fingers, one after another.

The means by which the pattern sheet is given the stepwise movement in the direction of its length is necessarily duplicated at each end of the machine so that when the pattern sheet has been moved in a direction transversely of its length as far as it may go in either direction, it is then advanced by one step longitudinally. When the pattern sheet has been carried to its limit of movement toward the left, the plate 262, together with the other associated mechanism causes the shift to be made from one pawl to another. As will be seen in Fig. 6, the shaft 165 is provided with a pair of plates 262, one at each end of the shaft, so that when the shaft is moved to the right to the limit of its movement, the plate 262 at the left-hand end of the shaft will be brought beneath the lug 260 on the arm 255, whereupon the arms 255 and 266, acting upon pawls 243 and 247 as the slides are moved, will cause the parts to operate in a manner similar to that caused by the action of the arms 253 and 254, but with the reverse effect as to the pawls. Consequently, the mechanism carried by the plate 222 which includes the arms 253, 254, 255 and 256, causes a reversal in the direction of travel of the shaft 165 at the appropriate instant. The means by which the pattern sheet is advanced in the direction of its length will now be described.

Mounted on a plate 265, in turn mounted on the bracket 220, is a plate 266 having a tongue which enters a dove-tail groove 267 in the upper face of the plate. The plate 267 is secured in adjusted position relative

to the plate 265 by means of screw 268, and in the upper surface of the plate 266 is a channel in which moves a lever 269. This lever is connected by a suitable pin connection to the upright arm of a bell crank 270, pivoted at any convenient location on the machine. The other arm of the bell crank carries a roller 271 bearing on a cam 272 on the main shaft of the machine, the movement of which causes the lever 267 to be reciprocated to and fro. A plate 273 secured to the upper surface of the plate 266 covers the channel in which the lever 269 reciprocates, and a spring 274 is attached at one end to the cover plate 273 and at the other to a projection on the lever 269, this spring tending to hold the lever in its retracted position so that the bell crank is rocked to hold its roller against the surface of the cam 272. On the outer end of the lever 269 there is pivoted a pawl 275 against the upper surface of which bears a leaf spring 276, this spring forcing the pawl downward against a stop pin 277, carried on the end of the lever 269. The pin connection between the inner end of the lever 269 and the upright arm of the bell crank permits the plate 266 to be moved to different positions of adjustment without interfering with the driving connection between the lever and the bell crank.

As previously described, the pattern sheet support includes a sprocket wheel 171, at either end, and on the outer face of each sprocket wheel is a ratchet wheel 172. The arrangement of the parts by which the pawl 275 is actuated, is such that this pawl may engage one of the teeth of the ratchet wheel 172 on the left-hand end of the pattern sheet support and the reciprocation of the arm 269 will cause the pawl 275 to advance the ratchet by one tooth whenever the pattern sheet support has moved to appropriate position.

The operating mechanism including the pawl 275 is duplicated at the other end of the machine, and it will be seen that these pawls are continuously reciprocating once per each revolution of the drive shaft. The pawls, however, produce no useful result until the pattern sheet support has been moved to proper position relative to one or the other of them, whereupon one of the pawls 275 will engage the ratchet and cause the pattern sheet support to be rotated by the amount of one tooth. The amount of travel of the pawl and the shape of the ratchet teeth is such that each step in the rotation of the pattern sheet support will advance the pattern sheet by one double row of effective areas, and these pawls are timed to operate during that period of the operation of the machine when the rotation of the cam 229 is causing the operation of the

mechanism by which the pattern sheet is said to be reversed.

From the description of the parts it will be seen that the pattern sheet is advanced past the fingers through which it exercises its control over the formation of the links with a step by step movement so that at each period of rest a different part of the pattern sheet is presented to these fingers and there are as many different parts so presented in a transverse movement of the pattern sheet as there are links in a row around the sleeve of mesh. At the end of the transverse travel of the pattern sheet it is advanced one step in the direction of its length, whereupon a return transverse movement, step by step, commences. This zig-zag travel of the pattern sheet is repeated indefinitely and upon each complete passage of the pattern sheet through the machine a sleeve of mesh having the selected pattern is produced. Successive passages of the pattern sheet result in the production of further quantities of mesh, each of which has the same pattern.

In Figs. 18 to 21, inclusive, there is shown a stationary wire guide block and a wire feeding mechanism to be used in connection with this type of block. The block illustrated in Fig. 16 is used on a machine for making mesh of three different kinds of wire and there are three passages 103 formed through this block by which the wire is to be delivered to the link-forming tools. In the block illustrated in Fig. 20, which is also used for three different kinds of wire, there are three inlet passages 278 which unite at the point 279 and there communicate with a single outlet passage 280. The length of the outlet passage is substantially equal to the amount of wire which is required for the formation of a single link, and with this type of block the outlet passage 280 is always in proper position to deliver wire to the link-forming tools. The wire from the several sources of supply pass through tubes 105, as before, from the feeding rolls to the block, and when the machine is started the wire is led from these rolls through the tubes, through the inlet passages to the point 279 at which these passages communicate with the outlet passage. When the feeding mechanism for one kind of wire is brought into action it feeds a length of wire sufficient for two links, but only that portion of the length fed which is sufficient for one link is projected beyond the end of the block, the remaining portion of the length so fed lying in the outlet passage 280. As the portion of the wire is projected beyond the end of the block the cutting knife comes into action, as before, and the severed length is engaged by the link-forming devices and inserted into the fabric. As soon as the

- knife has severed the exposed length of the wire, however, the feeding mechanism is reversed and retracts the wire to an extent sufficient to withdraw the length of wire 5 lying in the outlet passage to the rear of the point 279. Thus the outlet passage is cleared and if the next link is to be made of a different kind of wire, there will be no interference at this point.
10. The mechanism for producing a feeding movement of this kind is illustrated in Figs. 18 and 19. As before, the wire is led from the source of supply through a pair of grooved rolls 132 mounted in the block 134 15 and caused to move in unison by the intermeshing gears 138 and 139. Mounted on the shaft of the lower gear is a rocking arm 281, near the upper end of which is pivoted a pawl 282 held in its lowermost position 20 by a leaf spring 283. At the lower end of the arm 281, below its pivot point, is a second pawl 284, also spring-pressed by a spring 285. Fixed in the face of the block 134 above this pawl is a pin 286, and the 25 pawl has a cam surface 287 formed on its upper face. On the shaft of the lower feed roll there is mounted a toothed wheel 288, having square teeth spaced a considerable distance apart. Placed above the shaft of 30 the lower roll connected to the lever 281 above its pivot point on the shaft of the lower feed roll, is a link 144 which, in turn, is connected to one arm of the bell crank 145 as in the construction previously described. A control rod 150, carrying a pin 35 lying beneath the upper pawl 282, is used in order to render this pawl ineffective whenever required, and the rod 150 carries another pin 289 which lies beneath a dog 40 290 pivotally mounted on the bed plate of the machine at 291. The end of this dog has an upward extension 292 which bears against a tail 293 on the pawl 284. With this arrangement when the rod 150 is in its 45 lower position the upper pin permits the pawl 282 to drop down under the influence of its leaf spring into engagement with the teeth on the wheel 288 and the lower pin 289 permits the dog 290 to drop down. As 50 the bell crank 145 is rocked by its appropriate mechanism, it causes the arm 281 to rock and as the pawl 282 is moved forward it carries the toothed wheel 288 with it. The throw of the lever 281 is such that the 55 toothed wheel 288, and accordingly the feed rolls 132, will be advanced by two teeth on the wheel 288, thus feeding an amount of wire sufficient for two links. When the lever 281 moves backwardly the pawl 282 60 rides up over a tooth on the wheel 288 and at the proper instant the pawl 284 has been moved so that the cam surface 287 will move past the pin 286, thus permitting this pawl 284 to engage between the teeth on the 65 wheel 288. The pawl 284 tends to move the toothed wheel in the reverse direction, and the cam surface 287 is so formed relative to the pin 286 that the reverse movement of the wheel 288 will correspond to a single tooth on the wheel. Thus when the arm 281 70 is rocked the pawl 282 moves the wheel 288 so as to feed an amount of wire sufficient for two links, and on the return movement of the arm 281 the pawl 284 will cause the feed rolls to retract the wire by an amount 75 sufficient for the formation of a single link. Accordingly, when this feeding device is in operation wire is fed from the point 279, out through the outlet passage and is cut off even with the end of the wire block. 80 When this severance has occurred the wire is retracted by an amount sufficient to clear the outlet passage of the block.
- Whenever the feeding mechanism is to be rendered ineffective the rod 150 is raised, 85 the upper pin lifts the pawl 282 clear of the teeth of the wheel 288, and the lower pin 289 raises the dog 290 so that its end 292 bears against the tail 293 of the pawl 284, thus rocking this pawl on its pivot and forcing its forward end out of action. The devices by which this type of feeding mechanism is controlled are in all respects similar to those used in connection with the feeding mechanism used with the movable wire block, 90 except that in the case of the block having a single outlet passage this passage is always in registry with the link-forming tools and need not be placed in different positions, according to which kind of wire is being fed. 100
- From the foregoing description of the construction and operation of the machine, it will be seen that the utility of the invention is by no means limited to any specific number of supplies or wire, nor to any definite number of sets of link-forming tools which act simultaneously to add links to the piece of mesh; nor is the invention limited to any specific type of mesh-making machine, having here been illustrated in connection with a machine in which the mesh is made in the form of a cylindrical sleeve merely for the sake of clearness. In this machine there are two sets of link-forming tools, and each set of tools is supplied with wire 105 from one or another of three different supplies. If it were desirable, additional sets of link-forming tools could be employed. In that event additional supplies of wire would be required and associated with each of these 110 groups of wire supplies would be a finger, a cam plate, and control bar for determining which wire feeding device was to be operative at any particular instant in the progress of the mesh-making operation. Also a pattern sheet would be used having control areas arranged on it in multiple groups with as many different groups in a unit as there were control fingers, and consequently sets of link-forming tools. These multiple groups 115 120 125 130

of effective areas would be presented successively to the groups of fingers and, in general, the construction would simply involve a duplication of parts which have been 5 illustrated in the accompanying drawings and have previously been described.

If this machine were to be employed for making mesh having links of more than three kinds of wire incorporated in it, then 10 it would be necessary to provide additional kinds of effective areas. In the present machine the pattern sheet has been formed with blank spaces and perforations of two different sizes, thus providing for effective areas 15 which make it possible to give the control finger three different positions of rest, each of which corresponds to a different supply of wire. If four supplies were to be used, then the pattern sheet would have perforations of 20 three different kinds, the blank spaces providing the fourth position of rest of the finger. Also it would be necessary to form the finger so that it would assume different 25 positions of rest when cooperating with these perforated portions of the sheet. Instead of making the sheet with perforations, it is, of course, possible to make use of a sheet having projections or studs formed on it, which serve as control areas. These 30 projections would then be given varying heights so as to cause the finger to assume different positions of rest when in contact with them.

In the present machine the pattern sheet 35 is made of any suitable material, and perforated to produce the desired pattern in the mesh, and this sheet is so formed that its ends may be quickly secured together, thus making an endless belt or tape. The sheet is put in place on the support with the 40 perforations along its edge receiving the teeth of the sprocket wheels at either edge of the rotary support. Then the ends of the sheet are secured together in any convenient way and as the machine operates to produce 45 mesh the pattern sheet passes by the fingers with repeated cycles, thus producing pieces of mesh in which the desired pattern is formed with each of these pieces corresponding exactly with all of the others. When the machine is started the first row 50 of the pattern is brought into position under the fingers and opposite the channels in the stationary block between the sprocket wheels which form a part of the rotary support. 55 The support is then set by hand so that the first effective areas in a group or row are beneath the fingers. With the parts in this position the power shaft is connected to the driving means and the machine operates 60 automatically thereafter. Each link of the mesh is made of wire which has been determined in advance, and one of the areas on the pattern sheet is brought into control 65 position at each operation of the link-forming tools. Should the tools fail to insert a

link for any reason, as, for instance, because of a defect in the wire, the machine may be stopped, the parts turned back by the hand wheel so that this part of the mesh is again positioned beneath the tools, the 70 tools may then be operated by the rotation of the driving shaft by the hand wheel so as to insert the link at the point where the failure occurred, and thereafter the machine may be restored to its original setting and 75 the automatic mesh-making operation proceeds. When a sufficient amount of the mesh having the desired pattern has been produced, the machine is stopped, the ends of the pattern sheet disconnected and 80 slipped from the rotary support, and thereafter a new sheet may be put in position to produce a different kind of mesh. This operation is very simple and does not involve any complicated adjustments or the 85 dismantling of any part of the machine. Consequently, it may be carried on without interrupting the production of the mesh for an extended period.

In the present machine the mechanism is 90 arranged so that the pattern sheet is given a movement past the finger and when a predetermined point has been reached in the course of this movement, the pattern sheet is advanced by one step in the direction of 95 its length. It would be possible, and might in some cases be convenient, to alter the construction, as, for instance, by causing the pattern sheet to move simply with a step by 100 step longitudinal movement and to cause the fingers to move in a direction transversely of the pattern sheet, coming successively into contact with the effective control areas thereon. Also, it might be desirable under 105 some conditions, to make the pattern sheet 110 with groups of effective areas thereon which correspond to less than a complete row of links around the sleeve. For instance, it would be equally satisfactory to make the pattern sheet with groups of perforations, each of which corresponded to one half a 115 row of links, in which case the pattern sheet would be advanced twice in the direction of its length while a single row of links about the sleeve was being completed. Such changes as these, and various others which do not essentially alter the principles of 120 this invention, are contemplated by me, and are intended to be included within the scope of the claims annexed. In any machine involving the principles of the invention, it will be seen that there is a control member having effective control areas disposed thereon in groups in accordance with a predetermined pattern, a member which is movable to different positions of rest which are determined by the control areas on the first member and which, in turn, determine the supply from which wire is to be fed to the 125 link-forming tools, and means by which 130

these two members are given a relative movement such that the control areas in a group are successively presented to the second member as the mesh-making operation progresses, and then the next group is presented to the member with the areas of this group brought successively into such a position as to determine the position of rest of the member:

10 I claim:

1. A machine for making link mesh, which comprises the combination of a support for a piece of mesh, link-forming tools, power driven mechanism for giving the tools and the piece of mesh a step by step relative movement and for operating the tools in each period of rest of this movement, a plurality of supplies of wire link material, means for feeding material to the link-forming tools from each of these supplies, and control mechanism for determining the supply from which material is to be fed to the tools, including a pattern sheet having effective control areas disposed thereon in groups, a finger cooperating with the pattern sheet and movable to different positions of rest under the control of said area, means for giving the pattern sheet and the finger a step by step relative movement in correspondence with the formation of individual links and a second step by step movement in a different direction in correspondence with the formation of groups of links, and means under the control of said finger for rendering a selected feeding means operative while the others are inoperative.

2. A machine for making link mesh which comprises the combination of a support for a piece of mesh, link-forming tools, power driven mechanism for giving the tools and the piece of mesh a step by step relative movement and for operating the tools in each period of rest of this movement, a plurality of supplies of wire link material, means for feeding material to the link-forming tools from each of these supplies, and control mechanism for determining the supply from which material is to be fed to the tools including a pattern sheet having effective control areas disposed thereon in groups, a finger cooperating with the pattern sheet and movable to different positions of rest under the control of said areas, means for giving the pattern sheet and the finger a step by step relative movement in correspondence with the formation of individual links, and a second step by step movement in a different direction in correspondence with the formation of rows of links, and means movable to different positions of rest determined by the position of rest of said finger and operative in each such position of rest for rendering a selected feeding means operative while the others are maintained inoperative.

3. A machine for making link mesh which comprises the combination of a support for a piece of mesh, link-forming tools, power driven mechanism for giving the tools and the piece of mesh a step by step relative movement and for operating the tools in each period of rest of this movement, a plurality of supplies of wire link material, means for feeding material to the link-forming tools from each of these supplies and control mechanism for determining the supply from which material is to be fed to the tools, including a pattern sheet having effective control areas disposed thereon in groups, a control finger movable to different positions of rest under the control of said effective areas, means for giving the pattern sheet and the finger a relative step by step movement in one direction in accordance with the formation of individual links and for bringing the finger into contact with one of these areas at each step in this movement and also for giving the finger and the sheet a relative step by step movement in a different direction to bring the next group of areas and the finger into cooperating position, and means movable to different positions of rest determined by the position of rest of said finger when in contact with the pattern sheet, said means being operable to render a selected feeding means operative while the others are inoperative.

4. A machine for making link mesh which comprises the combination of a support for a piece of mesh, link-forming tools, power driven mechanism for giving the tools and the piece of mesh a step by step relative movement and for operating the tools in each period of rest of this movement, a plurality of supplies of wire link material, means for feeding material to the link-forming tools from each of these supplies and control mechanism for determining the supply from which material is to be fed to the tools, including a pattern sheet having effective control areas disposed thereon in groups, a control finger cooperating with the pattern sheet and movable to different positions of rest determined by these areas, means for moving the sheet and the finger relatively to present the control areas successively to the finger and a bar for controlling the action of a plurality of feeding means and movable to different positions of rest determined by the position of rest of the control finger when in cooperative relation to the pattern sheet, this bar being effective in each such position of rest to render a selected feeding means operative while maintaining the others inoperative.

5. A machine for making link mesh which comprises the combination of a support for a piece of mesh, link-forming tools, power driven mechanism for giving the tools and the piece of mesh a step by step relative

movement and for operating the tools in each period of rest of this movement, a plurality of supplies of wire link material, means for feeding material to the link-forming tools from each of these supplies, and control mechanism for determining the supply from which material is to be fed to the tools, including a pattern sheet having effective control areas disposed therein in 5 groups, a control finger movable to different positions of rest determined by the effective areas on the pattern sheet and corresponding in number to the number of supplies of different kinds of wire link material, means 10 for giving the pattern sheet and the finger a step by step relative movement and for bringing the finger into contact with one of the areas, at each pause in the movement, and a bar for controlling the action of a 15 plurality of feeding means and movable to different positions of rest determined by the position of rest of the control finger when in cooperative relation to the pattern sheet, this bar being effective in each such position of rest to render a selected feeding 20 means operative while maintaining the others inoperative.

6. A machine for making link mesh, which comprises the combination of a support for a piece of mesh, link-forming tools, power driven mechanism for giving the tools and the piece of mesh a step by step relative movement and for operating the tools in each period of rest of this movement, a plurality of supplies of wire, means for feeding wire from each supply to the tools, and a selector device for determining the kind of wire to be fed to the tools and including a pattern sheet having effective 25 control areas disposed thereon in groups, a control finger adapted to cooperate with these control areas and movable to different positions of rest determined by them, means for giving the pattern sheet and the control 30 finger a step by step relative movement in correspondence with the operation of the link-forming tools whereby the control areas are successively presented to the finger, means for bringing the finger into cooperating 35 position with the pattern sheet at each pause in the step by step relative movement whereby the finger assumes a position of rest determined by the effective areas then presented, the said means operating to remove 40 the finger from such cooperating position during the relative movement of the sheet and finger, means for actuating all of the wire-feeding means simultaneously, and means under the control of the control finger, for rendering a selected actuating means 45 operative to cause wire to be fed while the others are inoperative.

7. A machine for making link mesh, which comprises the combination of a support for a 50 piece of mesh, link-forming tools, power

driven mechanism for giving the tools and the piece of mesh a step by step relative movement and for operating the tools in each period of rest of this movement, a plurality of supplies of wire, means for feeding wire from each supply to the tools, and control mechanism for determining the supply from which the wire is fed to the tools, and including a pattern sheet having effective 55 control areas disposed thereon in parallel groups, a control finger cooperating with the pattern sheet and movable to different positions of rest determined by said effective areas, means for moving the pattern sheet and the control finger relatively with a step by step movement to cause the effective areas of successive groups to be presented to the finger one after another, means for bringing the finger into contact with a control area in the pauses in this step by step relative movement, and for moving the finger out of contact with the pattern sheet so that the step by step relative movement may take place, and means movable with the movements of the finger and adapted to render 60 one of the feeding means operative while the others are maintained inoperative, the feeding means rendered operative being determined by the position of rest of said finger.

8. A machine for making link mesh which comprises the combination of a support for a piece of mesh, link-forming tools, power driven mechanism for giving the tools and the piece of mesh a step by step relative movement and for operating the tools in each period of rest of this movement, a plurality of supplies of wire, means for feeding wire from each supply to the tools, and control mechanism for determining the supply from which wire is fed to the tools and including a pattern sheet having effective 65 control areas disposed thereon in groups, a control finger cooperating with the pattern sheet, means for moving the pattern sheet and the finger relatively with a step by step movement whereby to present the control areas successively to the finger, means for moving the finger into contact with the pattern sheet in the pauses in this step by step relative movement and for moving the control finger out of contact with the pattern sheet when a step in this relative movement is to take place, a control bar movable to different positions of rest and in each position of rest operable to render a selected feeding means operative, and connections between the control bar and the finger for causing the control bar to render all of the feeding means inoperative when the finger is out of contact with the sheet, and for bringing the control bar into a position such that one of the feeding means determined by the pattern sheet is rendered operative 70

when the finger is in contact with the pattern sheet.

9. A machine for making link mesh, which comprises the combination of a support for 5 a piece of mesh, link-forming tools, power driven mechanism for giving the tools and the piece of mesh a step by step relative movement and for operating the tools in each period of rest of this movement, a plurality of supplies of wire, means for feeding wire from each supply to the tools, and control mechanism for determining the supply from which the wire is to be fed to the tools and including a pattern sheet having 15 effective areas thereon disposed in groups, a control finger cooperating with the pattern sheet and movable to different positions of rest under the control of the latter, means for giving the pattern sheet and the control 20 finger a step by step relative movement such that successive control areas are presented one by one to the finger, means for lifting the finger out of contact with the sheet during each step in the movement and for 25 bringing the finger into contact with the sheet during the pauses in the step by step movement, and a control bar having a plurality of control surfaces thereon, each surface being effective in a different position of 30 the bar to render one of the feeding devices operative, and means for moving the bar to a position such that one of the surfaces will be in effective position, this position of the control bar being determined by the position 35 of rest of the control finger in contact with the pattern sheet.

10. A machine for making link mesh, which comprises the combination of a support for a piece of mesh, link-forming tools, 40 power driven mechanism for giving the tools and the piece of mesh a step by step relative movement and for operating the tools in each period of rest of this movement, a plurality of supplies of wire, means for feeding wire from each of the supplies to the link-forming tools, means for rendering one 45 of said feeding means operative while maintaining the others inoperative, a pattern sheet having effective control areas disposed thereon in parallel groups, and means controlled by the areas on the pattern sheet and in turn controlling the means by which the feeding means are rendered operative.

11. A machine for making link mesh, 55 which comprises the combination of a support for a piece of mesh, link-forming tools, power driven mechanism for giving the tools and the piece of mesh a step by step relative movement and for operating the tools in each period of rest in this movement, a plurality of supplies of wire, means associated with each supply for feeding wire therefrom to the link-forming tools, means operable with each operation of the link-forming tools for rendering all of the wire 60

feeding means inoperative and thereafter restoring one of these wire feeding means to operative condition, and a pattern sheet having effective control areas disposed thereon in parallel groups for controlling 70 the action of the last-named means, whereby the wire feeding means are rendered operative in accordance with the pattern carried by the pattern sheet.

12. A machine for making link mesh, 75 which comprises the combination of a support for a piece of mesh, link-forming tools, power driven mechanism for giving the tools and the piece of mesh a step by step relative movement and for operating the tools in each period of rest in this movement, a plurality of supplies of wire, means for feeding wire to the link-forming tools from each of these supplies, means operable upon each actuation of the link-forming tools for 80 rendering all of the wire feeding means inoperative and thereafter restoring one of these wire feeding means to operative condition, a control bar for controlling the action of the last-named means and movable 85 to different positions of rest, whereby such control is exercised, and a pattern sheet having effective areas disposed thereon in parallel groups, each of these effective areas serving to determine the position of rest of 90 the control bar.

13. A machine for making link mesh, which comprises the combination of a support for a piece of mesh, link-forming tools, 100 power driven mechanism for giving the tools and the piece of mesh a step by step relative movement and for operating the tools in each period of rest in this movement, a plurality of supplies of wire, individual means associated with each supply of wire 105 for feeding wire therefrom to the link-forming tools and including a pawl and ratchet, means for actuating all of the pawls in unison, and control mechanism for rendering one of the pawls operative and including 110 a pattern sheet having control areas disposed thereon in groups, and a control finger movable to different positions of rest determined by these control areas and in each position of rest serving to select and render 115 effective one of said pawls while the others are maintained inoperative.

14. A machine for making link mesh, which comprises the combination of a support for a piece of mesh, link-forming tools, 120 power driven mechanism for giving the tools and the piece of mesh a step by step relative movement and for operating the tools in each period of rest in this movement, a plurality of supplies of wire, individual means associated with each supply of wire 125 for feeding wire therefrom to the link-forming tools and including a pawl and ratchet, means for actuating all of the pawls in unison, and control mechanism for render- 130

ing one of the pawls operative and including a pattern sheet having control areas disposed thereon in groups, a control bar movable to different positions of rest and in each position operating to render one pawl operative while the others are maintained inoperative, and a finger interposed between the control bar and the pattern sheet and movable to different positions of rest determined by the control areas on the sheet and in turn determining the positions of rest of the control bar.

15. A machine for making link mesh which comprises the combination of a support for a piece of mesh, link-forming tools, power driven mechanism for giving the tools and the piece of mesh a step by step relative movement and for operating the tools in each period of rest in this movement, a plurality of supplies of wire, individual means associated with each supply of wire for feeding wire therefrom to the link-forming tools and including a pawl and ratchet, means for actuating all of the pawls in unison, and control mechanism for rendering all but one of the pawls inoperative and including a pattern sheet having control areas disposed thereon in groups, a control finger movable to different positions of rest determined by the control areas on the sheet, means for giving the finger and the sheet a relative step by step movement such that the control areas are successively presented to the finger in accordance with the progress of the mesh-making operation, and a control bar movable to different positions of rest determined by the positions of rest of the control finger and operable in each position of rest to select and render effective one of said pawls while the others are maintained inoperative.

40. A machine for making link mesh, which comprises the combination of a support for a piece of mesh, link-forming tools, power driven mechanism for giving the tools and the piece of mesh a step by step relative movement and for operating the tools in each period of rest in this movement, a plurality of supplies of wire, individual means associated with each supply for feeding wire therefrom to the link-forming tools and including a pawl and ratchet, means for actuating all of the pawls in unison, and control mechanism for rendering all but one of the pawls inoperative and including a pattern sheet having control areas disposed thereon in groups, a control finger movable to different positions of rest determined by the control areas, means for causing the control finger and the successive areas to be brought into cooperating relation whereby the finger assumes its positions of rest, a control bar having surfaces formed thereon, each of which is effective in a given position of rest of said bar to render one of the pawls effective while the others are maintained in-

effective, and operative connections between the bar and the finger such that the bar will assume positions of rest determined by the positions of rest of the finger in cooperative relation with the pattern sheet control areas. 70

17. A machine for making link mesh, which comprises the combination of a support for a piece of mesh, link-forming tools, power driven mechanism for giving the tools and the piece of mesh a step by step relative movement and for operating the tools in each period of rest in this movement, a plurality of supplies of wire, individual means associated with each supply for feeding wire therefrom to the link-forming tools and including a pawl and ratchet, means for actuating all of the pawls in unison, and control mechanism for rendering all but one of the pawls inoperative and including a pattern sheet having control areas disposed thereon in groups, a control finger movable to different positions of rest determined by these areas, means for giving the finger and the pattern sheet a step by step relative movement to cause successive areas on the sheet to be presented to the finger, means for bringing the finger and sheet into contact at each pause in this movement whereby the finger is caused to assume positions of rest determined by said areas, and also for moving the finger and sheet out of contact before the next step in the movement occurs, a control bar movable to different positions of rest determined by the position of rest of the finger and having surfaces thereon, each of which is effective in a given position of rest of the finger to render one of the pawls operative while the others are maintained inoperative, and operative connections between the bar and the finger so arranged that when the finger and sheet are out of contact the control bar will be moved to a position in which all the surfaces are ineffective to render the pawls operative, and when the finger is in contact with the sheet the control bar will assume a position of rest, determined by the position of rest of the finger, whereby a selected pawl is rendered operative. 90

18. A machine for making link mesh, which comprises the combination of a support for a piece of mesh, link-forming tools, power driven mechanism for giving the tools and the piece of mesh a step by step relative movement and for operating the tools in each period of rest in this movement, a plurality of supplies of wire, individual means associated with each supply of wire for feeding wire therefrom to the link-forming tools and including a pawl and ratchet, means for actuating all of the pawls in unison, and control mechanism for rendering all but one of the pawls inoperative and including a pattern sheet having control areas disposed thereon in groups, a control 120

finger movable to different positions of rest determined by these areas, means for giving the pattern sheet and the finger a step by step relative movement such that the control 5 areas are successively presented to the finger, means for moving the finger and the sheet into and out of cooperative relation during the pauses in their relative step by step movement, whereby the finger comes to a 10 position of rest determined by a control area on the sheet, a control bar having surfaces thereon each of which may be brought individually into operative position by a movement of the bar, each surface being 15 effective in one position of the bar to render one of the wire feeding pawls operative while the other pawls are inoperative, this control bar being movable in correspondence with the relative movement of the pattern 20 sheet and finger into and out of cooperative relation, and operative connections between the control bar and the finger so arranged that when the finger and pattern sheet are out of cooperative relation all of the control 25 bar surfaces are ineffective to render their associated pawls operative and when the cooperative relation between the pattern sheet and finger is restored, one of the control bar surfaces, determined by the position of rest 30 of the finger, will be effective to render its associated pawl operative to feed wire.

19. A machine for making link mesh which comprises the combination of a support for a piece of mesh, link-forming tools, 35 power driven mechanism for causing a relative step by step movement of the tools and the piece of mesh and for operating the tools in each period of rest of this movement, a plurality of supplies of wire, a pattern sheet 40 having control areas disposed thereon in groups, a control finger movable into contact with these areas and having different positions of rest determined by the areas, means for moving the pattern sheet past the 45 finger with a step by step movement to present the areas successively to the finger, means for moving the finger into and out of contact with the areas during the periods of rest of this step by step movement of the 50 pattern sheet, individual means for feeding wire from each of the supplies to the link-forming tools, each of these means including a pawl, means for actuating all of the pawls in unison in correspondence with 55 the operation of the link-forming tools, means for rendering one of these pawls operative while maintaining the others inoperative, and operative connections between the last-named means and the control finger 60 whereby the positions of rest of said finger control the action of said means and select the supply from which wire will be fed to the tools.

20. A machine for making link mesh 65 which comprises the combination of a sup-

port for a piece of mesh, link-forming tools, power driven mechanism for causing a relative step by step movement of the tools and the piece of mesh and for operating the tools in each period of rest of this movement, a plurality of supplies of wire, a pattern sheet 70 having control areas disposed thereon in groups, a control finger movable into contact with these areas and having different positions of rest determined by the areas, 75 means for moving the pattern sheet past the finger with a step by step movement to present the areas successively to the finger, means for moving the finger into and out of contact with the areas during the periods 80 of rest of this step by step movement of the pattern sheet, individual means for feeding wire from each of the supplies to the link-forming tools, each of these means including a pawl, a control bar having surfaces 85 thereon, each of which may be brought individually to operative position by a movement of the bar, in which position the said surface is effective to render one of the wire feeding pawls operative while the other 90 pawls are inoperative, a cam plate movable to different positions of rest and in each position serving to hold the control bar with one of its surfaces in operative position, and operative connections between the cam 95 plate and the finger for causing the cam plate to assume different positions of rest which are determined by the positions of rest of the finger in contact with a control area on the pattern sheet.

21. A machine for making link mesh which comprises the combination of a support for a piece of mesh, link-forming tools, power driven mechanism for causing a relative step by step movement of the tools in 105 each period of rest of this movement, a plurality of supplies of wire, a pattern sheet having control areas disposed thereon in groups, a control finger movable into contact with these areas and having different positions of rest determined by the areas, 110 means for moving the pattern sheet past the finger with a step by step movement to present the areas successively to the finger, means for moving the finger into and out of contact with the areas during the periods of rest of this step by step movement of the pattern sheet, individual means for feeding wire from each of the supplies to the link-forming tools, each of these means including a pawl, a control bar having surfaces 115 thereon, each of which may be brought into operative position by a movement of the bar so that this surface will render one of the pawls operative while the others are inoperative, a cam plate having a plurality of cam surfaces thereon, each of which may be brought to effective position to move the control bar to cause one of its surfaces to be placed in operative position, and operative 120

125 130

connections between the cam plate and the finger so arranged that when the latter is out of contact with the pattern sheet the cam plate and the control bar are moved to positions in which all of the surfaces on the control bar are out of operative position, thus rendering all of the wire-feeding pawls inoperative, and when the finger is in contact with the pattern sheet, the position of rest 5 of this finger, determined by the control areas on the pattern sheet, determines the position of rest of the cam plate and the control bar, whereby one of the surfaces on the control bar causes its associated pawl to be 10 rendered operative while the other pawls are inoperative.

22. In a machine for making link mesh, the combination with link-forming tools, of a plurality of supplies of wire, individual 20 means for feeding wire from each supply to the link-forming tools and including a continuously actuated pawl, and means for controlling the action of the wire feeding means and including a pattern sheet having effective areas thereon arranged in groups, a control finger movable into and out of contact with successive areas on the pattern sheet and assuming different positions of rest determined by these areas, a control bar 25 movable to different positions of rest and having effective areas thereon, each of which is effective in a different position of rest of the control bar for rendering one of the feed pawls operative while the others are maintained inoperative, a cam plate movable to different positions of rest and having a plurality of surfaces thereon, each of which is effective in one of the positions of rest of the cam plate to position the control bar 30 with one of its areas in effective position, means for moving the cam plate to a position in which it causes all of the control bar surfaces to be rendered ineffective, and means for restoring the cam plate to a position in 35 which it renders a selected control bar surface effective, this position being determined by the position of rest assumed by the finger in contact with the pattern sheet.

23. In a machine for making link mesh, the combination with link-forming tools, of a plurality of supplies of wire, individual 50 means for feeding wire from each supply to the link-forming tools and including a continuously actuated pawl, and means for controlling the action of the wire feeding means and including a pattern sheet having effective areas thereon arranged in groups, a control finger movable into and out of contact with successive areas on the pattern 55 sheet and assuming different positions of rest determined by these areas, a control bar having effective areas thereon, each of which is effective in a different position of rest of the control bar for rendering one of the feed pawls operative while the others are 60

maintained inoperative, a cam plate movable to different positions of rest and having surfaces against which the control bar bears, a rocking arm for moving the cam plate to present a surface thereon to the control bar 70 whereby all of the effective surfaces of the latter are rendered ineffective, the said arm causing this movement of the cam plate during the intervals in which the control finger is out of contact with the pattern sheet and 75 operative connection between the cam plate and the finger, including means by which the cam plate is restored to a position of rest such that one of the surfaces on the control bar is effective, this position of rest of the cam plate being determined by the position of rest of the finger in contact with the pattern sheet.

24. In a machine for making link mesh, the combination with link-forming tools, of a plurality of supplies of wire, individual 80 means for feeding wire from each of these supplies to the link-forming tools in correspondence with the actuation of the latter, a pattern sheet having effective areas disposed thereon in groups, a control finger movable to different positions of rest determined by the effective areas on the pattern sheet, means for moving the sheet and the finger relatively to cause successive areas to 85 be presented to the finger, a control bar operable to render one of the wire feeding devices operative while maintaining the others inoperative, a cam plate controlling the position of the control bar, and means 90 connected with the cam plate and operating to move the latter to different positions of rest determined by the position of rest of the finger in contact with the pattern sheet, whereby the cam plate will control the wire 95 feeding devices through the control bar.

25. In a machine for making link mesh, the combination with link-forming tools, of a plurality of supplies of wire, feed rolls associated with each supply, one of these feed 100 rolls having a ratchet wheel movable therewith, pawls adapted to engage these ratchet wheels, means for operating all of the pawls in unison in correspondence with the operation of the link-forming tools, a rod associated with each wire feeding device and operable to render its pawl inoperative, a control bar movable to different positions of rest and in each position effective to cause one of the rods to assume a position in which its associated pawl is operative while the other rods hold their associated pawls out of contact with their ratchet wheels, a cam plate 105 movable to different positions of rest and in each position determining the position of rest of the control bar, a pattern sheet having effective areas disposed thereon in groups, a control finger movable to different positions of rest which are determined by the areas 110 on the pattern sheet, means for causing a 115

relative movement of the pattern sheet and the finger whereby successive areas on the sheet are presented to the finger, and means acting on the cam plate to assume different 5 positions of rest which are determined by the position of rest of the finger in contact with the pattern sheet.

26. In a machine for making link mesh, the combination with link-forming tools, of 10 a plurality of supplies of wire, individual means associated with each of these supplies for feeding wire therefrom to the link-forming tools, a pattern sheet having effective areas disposed thereon in groups, a control 15 finger movable to different positions of rest determined by these areas and in each position of rest effective to render one of the wire feeding devices operative while the others are maintained inoperative, and 20 means for causing a step by step relative movement of the pattern sheet and the finger in a direction transversely of the length of the pattern sheet whereby successive areas in a group are presented to the 25 finger and also for causing a step by step relative movement of the sheet and the finger in the direction of the length of the sheet, one step in the latter movement occurring at a predetermined point in the first 30 movement.

27. In a machine for making link mesh, the combination with link-forming tools, of 35 a plurality of supplies of wire, individual means associated with each of these supplies for feeding wire therefrom to the link-forming tools, a pattern sheet having effective areas disposed thereon in groups, a control finger movable to different positions of rest determined by these areas and in each 40 position of rest effective to render one of the wire feeding devices operative while the others are maintained inoperative, means for causing a step by step relative movement of the pattern sheet and the finger 45 whereby successive areas in a row are presented to the finger, and continuously operating means effective for causing a step by step relative movement of the pattern sheet and the finger in the direction of the length 50 of the pattern sheet whenever a predetermined point in the course of the first relative movement has been reached, one step in this latter movement being sufficient to cause a new group of areas to be placed in 55 registry with the finger.

28. In a machine for making link mesh, the combination with link-forming tools, of 60 a plurality of supplies of wire, individual means associated with each of these supplies for feeding wire therefrom to the link-forming tools, a pattern sheet having effective areas disposed thereon in groups, a support 65 for the pattern sheet, a control finger movable to different positions of rest determined by the areas on the pattern sheet, means for

moving the pattern sheet support with a step by step movement in a direction transversely of the length of the pattern sheet whereby successive areas on the sheet are presented to the finger, and means effective 70 at a predetermined point in the movement of the support to cause the pattern sheet support to be given a movement such that the pattern sheet is advanced by one row in the direction of its length, whereby a 75 new group of areas is presented to the finger.

29. In a machine for making link mesh, the combination with link-forming tools, of 80 a plurality of supplies of wire, individual means associated with each of these supplies for feeding wire therefrom to the link-forming tools, a pattern sheet having effective areas disposed thereon in groups, a rotary pattern sheet support, a control finger 85 movable to different positions of rest determined by the areas on the pattern sheet, and in each position of rest operable to select and render operative one of the wire feeding means, while the others are maintained inoperative, means for moving the pattern sheet support longitudinally with a step by step movement to cause the control areas on the sheet to be successively presented to the finger, and means operating at 90 a predetermined point in the longitudinal movement of the support to cause the support to be rotated by an amount sufficient to present a new group of areas to the finger.

30. In a machine for making link mesh, the combination with link-forming tools, of 100 a plurality of supplies of wire, individual means associated with each of these supplies for feeding wire therefrom to the link-forming tools, a pattern sheet having effective 105 areas disposed thereon in groups, a rotary pattern sheet support, a control finger movable to different positions of rest determined by the areas on the pattern sheet, and in each position of rest operable to select and 110 render operative one of the wire feeding means while the others are maintained inoperative, means for moving the pattern sheet support with a longitudinal step by step movement in one direction so that areas 115 in one group are successively presented to the finger, and then for reversing the direction of the step by step movement, and means operating at a predetermined point 120 in the longitudinal movement of the support to cause the support to be rotated sufficiently to advance the pattern sheet by one group in the direction of its length, whereby the return longitudinal movement of the support will cause the areas in the next 125 succeeding group to be successively presented to the finger.

31. In a machine for making link mesh, the combination with link-forming tools, of 130 a plurality of supplies of wire, individual

- means associated with each of these supplies for feeding wire therefrom to the link-forming tools, a pattern sheet having effective areas disposed thereon in groups, a rotary pattern sheet support, a control finger movable to different positions of rest determined by the areas on the pattern sheet and in each position of rest operable to select and render operative one of the wire feeding means 5
- 10 while the others are maintained inoperative, means for moving the pattern sheet support with a longitudinal step by step movement, first in one direction and then the other, this means including a pair of pawls operable to move the support and brought successively into action whenever the pattern sheet support has been moved through a predetermined path, and means for rotating the support sufficiently to advance the pattern sheet in the direction of its length by one group, whereby the return movement of the pattern sheet will cause the areas in the next succeeding group to be successively presented to the finger.
- 15 25. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a rotary pattern sheet support, a control finger movable to different positions of rest determined by the areas on the pattern sheet and in each 20
- 30 position of rest operable to select and render operative one of the wire feeding means, while the others are maintained inoperative, means for moving the pattern sheet support longitudinally with a step by step movement 35
- 40 to cause the areas on the pattern sheet to be successively presented to the finger, this means including a pair of pawls operable to produce the movement of the pattern sheet support and brought into action in alternation at predetermined points in the longitudinal movement of the support, and means disposed at predetermined points in the path of travel of the pattern sheet support and operable whenever the pattern sheet support 45
- 50 reaches this point to produce a rotation of the support sufficient to cause the pattern sheet to be advanced to present a new group of areas to the finger.
- 55 33. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a rotary pattern sheet support having ratchet wheels 60
- 65 on either end, a control finger movable to different positions of rest determined by the effective areas on the pattern sheet and in each position of rest operable to select and

render operative one of the wire feeding means while the others are maintained inoperative, means for producing a step by step longitudinal movement of the pattern sheet support whereby successive areas on the sheet are presented to the finger, this means including a pair of pawls operable to produce a longitudinal movement of the pattern sheet support in opposite directions and brought into operation alternately at predetermined points in the longitudinal movement of the support, and a pair of pawls located at predetermined points in the longitudinal movement of the support and cooperating with the wheels on the support to cause a movement of rotation of the support sufficient to cause a new group of areas on the pattern sheet to be brought into operative position.

34. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet and in each position of rest operable to select and render operative one of the wire feeding means while the others are maintained inoperative, and means for producing a longitudinal step by step movement of the support whereby successive areas in a group may be presented to the finger, and including a rack shaft attached to the pattern sheet support, a pair of alternately operative pawls engaging this shaft and causing it to be advanced longitudinally with a step by step movement, and means operating at a predetermined point in the movement of the support for reversing the action of the pawls.

35. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet and in each position of rest operable to select and render operative one of the wire feeding means while the others are maintained inoperative, and means for producing a longitudinal step by step movement of the support whereby successive areas on the pattern sheet may be presented to the finger and including a rack shaft secured to the support, a pair of reciprocating slides, a pawl mounted on each slide and operable to engage the rack shaft and to move it by one tooth as the

slide reciprocates, and means operable whenever a predetermined point in the path of travel of the pattern sheet support has been reached for rendering one of the pawls inoperative and for bringing the other pawl into action.

36. In a machine for making link mesh, the combination with link-forming tools, of a plurality of supplies of wire, individual
10 means associated with each of these supplies for feeding wire therefrom to the link-forming tools, a pattern sheet having effective areas disposed thereon in groups, a pattern sheet support, a control finger movable to
15 different positions of rest determined by the effective areas on the pattern sheet and in each position of rest operable to select and render operative one of the wire feeding means while the others are maintained inoperative, and means for producing a longitudinal step by step movement of the pattern sheet whereby successive areas on the pattern sheet may be presented to the finger, and including a rack shaft secured to the
20 support, a pair of reciprocating slides, means for producing a reciprocation of these slides in correspondence with the operation of the link-forming tools, a pawl mounted on each slide and adapted to engage the rack shaft to cause the movement of the latter as the slide reciprocates, and means brought into action at a predetermined point in the path of longitudinal movement of the rack shaft and operating to cause successive relative movements of the slides and pawls such that the pawl engaging with the rack shaft is put out of operation and the other pawl is rendered effective upon the second reciprocation of the slides thereafter.

40 37. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet and in each position of rest operable to select and render operative one of the wire feeding means while the others are maintained inoperative, and means for producing a longitudinal step by step movement of the pattern sheet whereby successive areas on the pattern sheet may be presented to the finger, and including a rack shaft secured to the support, a pair of reciprocatory slides, means 55 for producing a reciprocation of these slides in correspondence with the operation of the link-forming tools, a pawl pivotally mounted on each slide and movable into a position where it engages the teeth on the rack shaft 60 and causes a movement of the latter with 65

the slide, a plate on each slide movable to cause the pawl thereon to be rocked on the slide into and out of operative relation with the rack shaft, and means operable at a pre-determined point in the path of travel of the rack shaft for moving these plates successively, whereby one pawl is put out of action and the other pawl brought into action thereafter. 70

38. In a machine for making link mesh, the combination with link-forming tools of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet and in each position of rest operable to select and render operative one of the wire feeding means while the others are maintained inoperative, and means for producing a longitudinal step by step movement of the pattern sheet whereby successive areas on the pattern sheet may be presented to the finger, and including a rack shaft secured to the pattern sheet support, a pair of reciprocatory slides, means for producing a reciprocation of these slides in correspondence with the operation of the link-forming tools, a pawl pivotally mounted on each slide and movable into a position where it engages the teeth on the rack shaft and causes a movement of the latter with the slide, a plate on each slide movable to cause the pawl thereon to be rocked on its pivot into and out of operative relation with the rack shaft, and means operable whenever a predetermined point in the path of travel of the rack shaft has been reached for causing a relative movement of these plates on the slides, these movements occurring in succession, whereby the operative pawl is rendered inoperative and the inoperative pawl thereafter brought into action, the slides making one movement, corresponding to the operation of the link-forming tools, while neither pawl is effective to produce a movement of the rack shaft.

39. In a machine for making link mesh, the combination with link-forming tools of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet and in each position of rest operable to select and render operative one of the wire feeding means while the others are maintained inoperative, and means for producing a longitudi- 130

nal step by step movement of the pattern sheet support in correspondence with the operation of the link-forming tools, whereby successive areas on the pattern sheet are presented to the finger and including a rack shaft secured to the pattern sheet support, a pair of pawls cooperating with the rack shaft and causing a step by step movement of the latter, and means brought into action at a predetermined point in the movement of the rack shaft for putting the operative pawl out of action and for bringing the inoperative pawl into action, whereby the direction of the movement of the rack shaft is reversed, the rack shaft remaining stationary for a period corresponding to one operation of the link-forming tools between the end of its movement in one direction and the beginning of its movement in the other direction.

40. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a rotary pattern sheet support, a control finger movable to different positions of rest determined by the effective areas on the pattern sheet and in each position of rest operable to select and render operative one of the wire feeding means while the others are maintained inoperative, means for producing a longitudinal step by step movement of the pattern sheet support in correspondence with the operation of the link-forming tools, whereby successive areas on the pattern sheet are presented to the finger, and including a rack shaft secured to the pattern sheet support, a pair of pawls cooperating with the rack shaft and causing a step by step movement of the latter, means brought into action at a predetermined point in the movement of the rack shaft for putting the operative pawl out of action, and for bringing the inoperative pawl into action, whereby the direction of the movement of the rack shaft is reversed, the rack shaft remaining stationary for a period corresponding to one operation of the link-forming tools between the end of its movement in one direction and the beginning of its movement in the other, and means operative in the interval when the rack shaft is stationary for causing a rotation of the pattern sheet support sufficient to bring the next group of areas into registry with the finger, this means including a ratchet wheel on either end of the pattern sheet support and a pair of pawls disposed near either end of the path of travel of the pattern sheet support and cooperating with the ratchet wheels.

41. In a machine for making link mesh, the combination with link-forming tools, of a plurality of supplies of wire, individual means associated with each of these supplies for feeding wire therefrom to the link-forming tools, a pattern sheet having ef-

fective areas disposed thereon in groups, a rotary pattern sheet support, a control finger movable to different positions of rest determined by the effective areas on the pattern sheet and in each position of rest operable to select and render operative one of the wire feeding means while the others are maintained inoperative, means for producing a longitudinal step by step movement of the pattern sheet support in correspondence with the operation of the link-forming tools, whereby successive areas on the pattern sheet are presented to the finger and including a rack shaft secured to the pattern sheet support, a pair of pawls cooperating with the rack shaft and causing a step by step movement of the latter, means brought into action at a predetermined point in the movement of the rack shaft for putting the operative pawl out of action, and for bringing the inoperative pawl into action, whereby the direction of the movement of the rack shaft is reversed, the rack shaft remaining stationary for a period corresponding to one operation of the link forming tools between the end of its movement in one direction and the beginning of its movement in the other, and means operative in the interval when the rack shaft is stationary for causing a rotation of the pattern sheet support sufficient to bring the next group of areas into registry with the finger, this means including a ratchet wheel on either end of the pattern sheet support and a pair of pawls disposed near either end of the path of travel of the pattern sheet support and cooperating with the ratchet wheels.

42. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet and in each position of rest operable to select and render operative one of the wire feeding means while the others are maintained inoperative, and means for producing a longitudinal step by step movement of the pattern sheet support in correspondence with the operation of the link-forming tools, whereby successive areas on the pattern sheet are presented to the finger and including a rack shaft secured to the pattern sheet support, a pair of slides reciprocated in correspondence with the operation of the link-forming tools, a pawl pivoted on each slide and adapted to engage with the rack shaft to move the latter as the slide moves, a plate on each slide movable to rock the pawl on its pivot into and out of operative re-

lation with the rack shaft, and means including a pair of rocking arms brought successively into action whenever a predetermined point in the path of travel of the rack shaft has been reached for engaging the plates and moving them successively to different positions on the slides, such that the effective pawl is rendered ineffective, and the ineffective pawl is brought into action.

43. In a machine for making link mesh, the combination with link-forming tools of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet and in each position of rest operable to select and render operative one of the wire feeding means while the others are maintained inoperative, means for producing a longitudinal step by step movement of the pattern sheet support in correspondence with the operation of the link-forming tools, whereby successive areas on the pattern sheet are presented to the finger and including a rack shaft secured to the pattern sheet support, a pair of slides reciprocated in correspondence with the operation of the link-forming tools, a pawl pivoted on each slide and adapted to engage with the rack shaft to move the latter as the slide moves, a plate on each slide movable to rock the pawl on its pivot into and out of operative relation with the rack shaft, and a pair of rocking arms brought successively into action whenever a predetermined point in the path of travel of the rack shaft has been reached for engaging the plates and moving them successively to different positions on the slides, such that the effective pawl is rendered ineffective, and the ineffective pawl is brought into action, these arms being operable to permit a reciprocation of the slides during which each of the pawls is out of action whereby the pattern sheet support is held stationary at the end of its longitudinal movement during one operation of the link-forming tools.

44. In a machine for making link mesh, the combination with link-forming tools of a plurality of supplies of wire, individual means associated with each of these supplies for feeding wire therefrom to the link-forming tools, a pattern sheet having effective areas disposed thereon in groups, a pattern sheet support, a control finger movable 55 to different positions of rest determined by the effective areas on the pattern sheet and in each position of rest operable to select and render operative one of the wire feeding means while the others are maintained 60 inoperative, and means for producing a 65

longitudinal step by step movement of the pattern sheet support in correspondence with the operation of the link-forming tools, whereby successive areas on the pattern sheet are presented to the finger and including a 70 rack shaft secured to the pattern sheet support, a pair of slides reciprocated in correspondence with the operation of the link-forming tools, a pawl pivoted on each slide and adapted to engage with the rack shaft 75 to move the latter as the slide moves, a plate on each slide movable to rock the pawl on its pivot into and out of operative relation with the rack shaft, and pairs of arms disposed near either end of the slides, one 80 set of arms being brought into action when a predetermined point in the path of travel of the rack shaft has been reached in either direction, each pair of arms being then operative to cause successive movements of the 85 plates relative to the slides such that the pawls are rocked on their pivots and the operative pawl is first rendered inoperative and the inoperative pawl thereafter brought into action. 90

45. In a machine for making link mesh, the combination with link-forming tools, of a plurality of supplies of wire, individual means associated with each of these supplies for feeding wire therefrom to the link-forming tools, a pattern sheet having effective areas disposed thereon in groups, a pattern sheet support, a control finger movable to different positions of rest determined by the effective areas on the pattern sheet 95 and in each position of rest operable to select and render operative one of the wire feeding means while the others are maintained inoperative, means for producing a longitudinal step by step movement of the pattern sheet support in correspondence 100 with the operation of the link-forming tools, whereby successive areas on the pattern sheet are presented to the finger and including a rack shaft secured to the pattern sheet support, a pair of slides reciprocated in correspondence with the operation of the link-forming tools, a pawl pivoted on each slide and adapted to engage with the rack shaft 105 to move the latter as the slides moves, a plate on each slide movable to rock the pawl on its pivot into and out of operative relation with the rack shaft, and pairs of arms disposed near either end of the slides, one set of arms being brought into action when a predetermined point in the path of travel of the rack shaft has been reached in either direction, each pair of arms being then operative to cause successive movements of the plates relative to the slides such that the pawls are rocked on their pivots and the operative pawl is first rendered inoperative and the inoperative pawl thereafter brought into action. 110

pawl on its pivot into and out of operative relation with the rack shaft, a pair of rocking arms brought into action whenever a predetermined point in the path of travel of the rack shaft has been reached for engaging the plates and moving them successively to different positions on the slides, such that the effective pawl is brought into action, these arms being operable to permit a reciprocation of the slides during which each of the pawls is out of action whereby the pattern sheet support is held stationary at the end of its longitudinal movement during one operation of the link-forming 130

tools, and means operating during this period of rest of the pattern sheet support to cause a movement of the pattern sheet support sufficient to present a new group of areas to the finger.

46. In a machine for making link mesh, the combination with link-forming tools, of a plurality of supplies of wire, individual means associated with each of these supplies 10 for feeding wire therefrom to the link-forming tools, a pattern sheet having effective areas disposed thereon in groups, a rotary pattern sheet support, a control finger movable to different positions of rest determined by the effective areas on the pattern sheet and in each position of rest operable to select and render operative one of the wire feeding means while the others are maintained inoperative, means for producing a 15 longitudinal step by step movement of the pattern sheet support in correspondence with the operation of the link-forming tools, whereby successive areas on the pattern sheet are presented to the finger and including a rack shaft secured to the pattern sheet support, a pair of slides reciprocated in correspondence with the operation of the link-forming tools, a pawl pivoted on each slide and adapted to engage with the rack shaft 20 25 30 35 40 45 50
- to move the latter as the slide moves, a plate on each slide movable to rock the pawl on its pivot into and out of operative relation with the rack shaft, a pair of rocking arms brought successively into action whenever a predetermined point in the path of travel of the rack shaft has been reached for engaging the plates and moving them successively to different positions on the slides, to reverse the action of the pawls, these arms being so arranged as to permit a reciprocation of the slides during which each of the pawls is out of action whereby the pattern sheet support is held stationary at the end of its longitudinal movement during one operation of the link-forming tools, continuously operating pawls for causing a movement of rotation of the pattern sheet support sufficient to advance the pattern sheet to present a new group of areas to the finger, these pawls being effective to rotate the pattern sheet support during the period of rest of the longitudinal movement of the support.
47. In a machine for making link mesh containing links of different kinds of wire, the combination of a plurality of supplies of wire, a ratchet and pawl associated with each supply and operable to cause wire to be drawn therefrom, and mechanism for selecting 55 60 65 70 75 80 85 90 95 100 105 110 115 120 125 130 the kind of wire to be fed and including a pattern sheet having a plurality of control areas formed thereon in groups, a finger movable to different positions of rest determined by the areas on the pattern sheet, a control bar having a plurality of surfaces

thereon, this control bar being movable to different positions of rest and in each position having one of the surfaces disposed in a position such that it causes one of the pawls to be placed in operative position relative to its ratchet, and a cam plate controlling the position of rest of said control bar, the action of the cam plate being controlled by the position of rest of the finger determined by the control areas on the pattern sheet.

48. In a machine for making link mesh containing links of different kinds of wire, the combination of a plurality of supplies of wire, a ratchet and pawl associated with each supply and operable to cause wire to be fed therefrom, movable means engaging the pawls and operable to control their operative relation with their ratchets, a control bar movable to different positions of rest and in each such position causing the pawl control means to render one pawl operative while maintaining the others inoperative, a pattern sheet having effective control areas disposed thereon in groups, a finger movable to different positions of rest determined by these control areas, a cam plate determining the position of rest of the control bar and thus controlling the supply from which material will be fed, and operative connections between the cam plate and the finger by which the action of the cam plate is controlled by the position of rest of the finger determined by the areas on the pattern sheet.

49. In a machine for making link mesh containing links of different kinds of wire, the combination of a plurality of supplies of wire, a ratchet and pawl associated with each supply and operable to cause wire to be fed therefrom, and control mechanism for selecting the kind of wire to be fed and including a pattern sheet having effective control areas disposed thereon in groups, a finger movable to different positions of rest determined by the control areas on the pattern sheet, a cam plate movable to different positions of rest determined by those of the finger, a control bar movable to different positions of rest determined by the cam plate, this control bar having surfaces thereon each of which is operable in a different position of rest of the control bar for placing one of the pawls in operative relation to its ratchet, while the other pawls are maintained out of such operative relation, means interposed between the surfaces on the control bar and the pawls for causing the pawls to be brought into action in accordance with the position of the control bar, means for moving the finger into contact with the effective areas on the pattern sheet, and means acting on the cam plate and operable when the control finger is out of contact with the pattern sheet to move the latter to such position that the control bar is moved

to a position in which all of the pawls are rendered inoperative.

50. In a machine for making link mesh containing links of different kinds of wire, the combination of a plurality of supplies of wire, means for incorporating links of wire from any supply in the mesh, and means for selecting the wire to be incorporated according to a predetermined pattern 10 and including a pattern sheet having effective control areas disposed thereon in parallel groups, a finger movable to different positions of rest determined by the control areas and in such positions of rest effective to 15 cause wire to be fed from a selected supply, and means for producing a step by step relative movement of the finger and the pattern sheet, such that the effective areas of the pattern sheet are brought successively into 20 action, group by group.

51. In a machine for making link mesh containing links of different kinds of wire, the combination of a plurality of supplies of wire, means for incorporating links of wire from 25 any supply in the mesh, and means for selecting the wire to be incorporated and including a pattern sheet having groups of areas of different forms arranged thereon in parallel lines corresponding to the number 30 of different kinds of wire to be fed, a control finger movable to different positions of rest determined by the form of the control area with which the finger is to contact and in such position of rest acting to cause wire to 35 be fed from one of the supplies to the link-incorporating means, and means for causing a step by step relative movement of the pattern sheet and the control finger such that the areas in each group on the pattern sheet 40 are successively presented to the finger.

52. In a machine for making link mesh, the combination of a pattern sheet having effective areas disposed thereon in groups, a control finger movable to different positions 45 of rest in contact with the said areas, means for giving the sheet and the finger a step-by-step relative movement such that the groups of effective areas are brought successively into cooperating relation to the finger and the areas in each group successively 50 presented to the finger, and means for bringing the finger into and out of contact with the areas so presented during the pauses in the step-by-step movement.

55. 53. In a machine for making link mesh containing links of different kinds of wire, the combination of a plurality of supplies of wire, means for incorporating links of any material in the fabric, and means for selecting the material to be used and including 60 a pattern sheet having blank spaces and perforations of different sizes constituting control areas, the different kinds of perforations being one less in number than the 65 number of different kinds of wire to be

used, a control finger movable to different positions of rest determined by the areas on the pattern sheet and having a portion adapted to bear against a blank space on the sheet, and another portion spaced from the 70 first and adapted to bear against the pattern sheet at the edge of a perforation while the first-named portion enters said perforation, and means controlled by the position of rest of said finger, determined by its contact with the pattern sheet, for causing wire to be fed from a selected supply to the link-incorporating means. 75

54. In a machine for making link mesh, the combination of a supply of wire, and means for feeding wire therefrom including a ratchet, a pawl operable to advance the ratchet by a double step, and another pawl operable when the first pawl is out of operation to retract the wire by a single step. 80

55. In a machine for making link mesh containing links of different kinds of wire, the combination of link-forming tools, a plurality of supplies of wire, a ratchet associated with each supply of wire, a pawl cooperating with the ratchet and adapted to advance the latter by a double step, a second pawl cooperating with the ratchet and adapted to cause the latter to move in the reverse direction by a single step, the 90 second pawl coming into action while the first pawl is out of action, and a wire block having a plurality of inlet passages therethrough, through each of which wire is fed from a different supply, and a single outlet passage with which all of the inlet passages communicate. 95

56. A wire block for use in a machine for making link mesh containing different kinds of wire, which comprises a body portion, a plurality of inlet passages formed therein, and corresponding in number to the number of different kinds of wire of which the mesh is to be made, and a single outlet passage with which all of the inlet passages communicate. 105

57. A wire block for use in a machine for making link mesh containing different kinds of wire, which comprises a body portion, a plurality of inlet passages corresponding in number to the number of different kinds of wire to be fed, and a single outlet passage with which each of the inlet passages communicates, the point of communication of the inlet passages with the outlet passage lying spaced from the discharge end of the outlet passage by a distance equivalent to the length of wire required for the formation of a single link. 115

58. In a machine for making link mesh containing links of different kinds of wire, the combination of a pattern sheet, a rotary support therefor, and means for advancing the support longitudinally step by step through a predetermined distance and for 125

- causing the support to be rotated one step at the end of this longitudinal movement.
59. In a machine for making link mesh containing links of different kinds of wire, the combination of a pattern sheet having control areas disposed thereon in groups, a control finger movable to different positions of rest determined by these areas, a rotary support for the pattern sheet, means for advancing the support with a step by step movement to present the areas in a group on the sheet successively to the finger, means for reversing the direction of the step by step movement of the support, and means for causing a rotary movement of the support at the end of the longitudinal movement in either direction whereby the areas in successive groups are presented successively to the finger, but in reverse order. 70
60. In a machine for making link mesh containing links of different kinds of wire, the combination of a pattern sheet, a support therefor, a rack shaft secured to the support, a pair of reciprocatory slides, a pawl on each slide, means for causing one pawl to engage with the teeth of the rack shaft and to produce a step by step movement of the latter in one direction as the slide on which that pawl is mounted reciprocates, and means for rendering this pawl effective and for bringing the other into action at a predetermined point in the path of travel of the support. 80
61. In a machine for making link mesh containing links of different kinds of wire, the combination of a pattern sheet, a support therefor, a rack shaft secured to the support, a pair of reciprocatory slides, a pawl on each slide, means for causing one pawl to engage with the teeth of the rack shaft and to produce a step by step movement of the latter in one direction as the slide on which that pawl is mounted reciprocates, and means for rendering this pawl effective 90
- 40 to engage with the teeth of the rack shaft and to produce a step by step movement of the latter in one direction as the slide on which that pawl is mounted reciprocates, and means for rendering this pawl effective 100
- 45 and for bringing the other into action at a predetermined point in the path of travel of the support, and including pairs of arms disposed near either end of the slides and brought into action by means carried by the 110
- 50 rack shaft, these arms being operable when brought into action to cause one pawl to be rocked on its slide to inoperative position and the other to be rocked on its slide to operative position with relation to the rack shaft. 115
62. In a machine for making link mesh containing links of different kinds of wire, the combination of a pattern sheet having effective areas disposed thereon in groups, a control finger movable to different positions of rest determined by these areas, means for moving the finger and the pattern sheet step by step with a relative movement such that the areas are successively presented to the finger, and including a pair of pawls 120
- 65 alternately operable to produce the relative movement of the pattern sheet and the finger in opposite directions, and means operating at a predetermined point in the course of the relative movement for reversing the action of the pawls. 75
63. A machine for making link mesh which comprises the combination of a support for a piece of mesh, a plurality of sets of link-forming tools, power driven mechanism for giving the tools and the piece of mesh a step-by-step relative movement and for operating the tools in each period of rest of this movement, a plurality of supplies of wire link material, means for feeding this material from the supplies to the link-forming tools, and a selecting means operated by the power driven mechanism for selecting the supply from which the material is to be fed, and including a member having effective areas arranged thereon in multiple rows, one row for each set of tools, the position of the areas in a row corresponding to the position of the links in a row in the piece of mesh, and means controlled by the areas in each row for controlling the means for feeding the material to a set of tools. 85
64. In a machine for making link mesh containing links of different kinds of wire, the combination of a rotary support, a flexible control element carried by the support, and means for actuating the support to produce a step-wise longitudinal movement of said support alternating with a step-wise longitudinal movement of said element. 95
65. In a machine for making link mesh containing links of different kinds of wire, the combination of a flexible control element, feeding devices for feeding wire, a member contacting with the element and controlling the operation of said feeding devices, and means for producing a step-by-step zig zag relative movement of said member and element. 100
66. In a machine for making link mesh containing links of different kinds of wire, the combination of a flexible control element, a rotary support therefor, feeding devices for feeding wire, a member controlled by said element and itself controlling said feeding devices and means for actuating the support to produce a longitudinal movement of said support alternating with a longitudinal movement of said element. 110
67. In a machine for making link mesh of different kinds of wire, the combination of a pattern sheet, a support therefor, and means for moving the sheet lengthwise and laterally in alternate movements. 120
68. In a machine for making link mesh of different kinds of wire, the combination of a flexible pattern sheet of indefinite length, a support therefor, and means for actuating said support to produce alternate longitudinal and lateral movements of said sheet. 125
- 65 130

69. In a machine for making link mesh of different kinds of wire, the combination of a control element of indefinite length, a support for a portion of said element, and means for actuating the support to give it an alternate axial and rocking movement.

70. In a machine for making link mesh of different kinds of wire, the combination of a control sheet wire feeding devices, a member adapted to enter openings in said sheet and to come to rest in a position determined thereby, means controlled by said member for controlling the feeding devices, and means for producing alternate longitudinal and lateral relative movements of said sheet and member.

71. The combination in a multi-colored mesh producing machine of a flexible pattern element having control areas, a member adapted to come to rest in contact with said areas, wire feeding devices controlled by said member, and means for producing a relative movement of said element and member alternately in directions lengthwise and transverse of said element.

72. The combination in a multi-colored mesh producing machine of a pattern element having control apertures, a support over which said element lies, a recess formed in said support, a member adapted to enter said apertures and recess and means for moving the element and member relatively to present successive apertures to the member.

73. The combination in a multi-colored mesh producing machine of a pattern sheet, a cylindrical support on which a portion of the sheet rests and means for producing alternate longitudinal and lateral movements of said sheet.

74. The combination in a multi-colored mesh producing machine of a pattern sheet, a cylindrical support on which a portion of the sheet rests, a member adapted to be brought into contact with the sheet, wire feeding devices controlled by the member and means for giving the support alternate axial and rotary movements relative to said member.

In testimony whereof I affix my signature.
50 FRED SWEETING.
